UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed March 22, 1918, Serial No. 224,072. Renewed May 12, 1923. Serial No. 552,598.

To all whom it may concern:

Be it known that I, MORRIS P. HOLMES, a citizen of the United States, residing at Claremont, in the county of Sullivan and State of New Hampshire, have invented certain new and useful Improvements in Mining Machines, of which the following is a full, clear, and exact specification.

This invention relates to mining machines, and especially to machines of the chain cutter type, which are fed along the face in which the cut is being made, and has for its general objects to improve and render more flexible, convenient, reliable, and efficient the mechanism for feeding the machine and the means for controlling said feeding mechanism; more particular objects being to render said feeding mechanism capable of propelling the machine at any one of a plurality of speeds and in either direction with equal facility, to provide means whereby the feeding mechanism may be caused to turn the machine as well as propel the same, to provide improved automatic releasing means for insuring the mechanism against breakage in case of overload, and also to co-ordinate the controlling devices in such a manner as to reduce to a minimum the possibility of improper operation of the apparatus.

The foregoing and other objects of the invention, together with means whereby the same may be carried into effect, will best be understood from the following description of certain forms or embodiments thereof shown for purposes of illustration in the accompanying drawings.

In said drawings,—

Fig. 1 is a plan view of the complete machine with the cutter bar partly broken away.

Fig. 2 is a side elevation of the parts shown in Fig. 1 with the side of the gear casing partly broken away.

Fig. 3 is a longitudinal section on the line 3—3 of Fig. 1.

Fig. 4 is a plan view, on an enlarged scale, of the transmission mechanism.

Fig. 5 is a transverse vertical section substantially on the line 5—5 of Fig. 4.

Fig. 6 is a partial longitudinal vertical section on the line 6—6 of Fig. 4.

Fig. 7 is a transverse vertical section substantially on the line 7—7 of Fig. 4.

Fig. 8 is an elevation of the upper part of

the rear end of the machine as viewed from the line 8—8 of Fig. 2.

Fig. 9 is a detail vertical section substantially on the line 9—9 of Fig. 4.

Fig. 10 is a detail horizontal section of the overload releasing device, taken substantially on the line 10—10 of Figs. 6 and 7.

Fig. 11 is a detail vertical section substantially on the line 11—11 of Fig. 10.

Fig. 12 is a fragmentary horizontal sectional view showing a modified form of overloading releasing device.

Fig. 13 is a detail vertical section of a further modification.

Fig. 14 is a diagrammatic view illustrating the operation of the machine.

Fig. 15 is a fragmentary plan view showing the means for turning the machine.

Fig. 16 is a detail illustration of the connecting member shown in Fig. 15.

Fig. 17 is a diagrammatic view of another sumping arrangement adapted to use under certain conditions.

Fig. 18 is a diagrammatic view of still another arrangement for sumping.

Fig. 19 is a diagrammatic view of a preferred arrangement for finishing a rib, showing the machine in two positions.

Fig. 20 is a diagrammatic view similar to Fig. 14 showing one arrangement when cutting in the opposite direction, i. e. from left to right.

In Figs. 1 and 2 is illustrated a mining machine of the familiar room and pillar type. This machine, as is usual in machines of its type, comprises a body from the forward end of which projects a fixed cutter bar 22 carrying a cutter chain 23, said body comprising a motor casing 20 and a gear casing 21 and having at its bottom a shoe 25 or base plate 24 upon which the machine is slid across the mine floor, as the cut progresses. Within the motor casing 20 is an electric or other motor 25 which operates, through transmission mechanism herein-after described, to actuate the cutter chain 23 and the feeding means for the apparatus, said feeding means including a feed chain 26 secured at its ends, as at A and B, Fig. 14, to suitable jacks or other securing devices at opposite ends of the path of travel of the machine, said chain passing over a guide roller or sprocket 27 at the rear of the machine, a feed sprocket 28 within the casing 21, and guide rollers or sprockets 29 and 30.

30 at the side of the machine adjacent the rear and front ends thereof, respectively. The parts thus far referred to, as to their general organization, arrangement, and 5 function, are well known in the art.

In accordance with the present invention, two pairs of guide rollers or sprockets 29, 30 are provided, one at each side of the machine, and with either pair of which the 10 single feed chain 26 may be engaged, said chain being, in both positions, operated by the same feed sprocket 28, which may be driven, through the medium of improved reversible actuating mechanism hereinafter 15 described, in either direction, thereby causing said chain to propel the machine across the mine floor in either direction; the feed chain during transverse or lateral cutting from right to left having its advance portion 20 extended from the feed sprocket or feed operating member 28 around the left hand rear guide 29 and forward to the front left hand guide 30 and then laterally therefrom to a fixed point at the left hand rib, 25 while its receding portion extends from the feed operating member 28 around the rear guide 27 and laterally therefrom to the right hand rib, and the construction also being such that when it is desired to reverse the 30 arrangement to permit cutting from left to right, the receding portion may be readily and quickly extended around the right hand rear guide 29 and forward therefrom and around the right hand front guide 30 to the 35 right hand rib as the advance portion, while the advance portion may be passed from the feed operating member 28 around the left guide 29 and laterally to the left hand rib as the receding portion.

40 Referring to Figs. 2, 3 and 5 the shaft 31 of the motor 25 is provided with a beveled gear 32 which meshes with a beveled gear 33 secured to a hub 39 which is in turn splined to a vertical shaft 34 journaled in suitable 45 bearings 35 and 36 carried, respectively, by the base of the casing 21 and by a cap piece 37 supported by suitable framing 38 within said casing. The hub 39 of the gear 33 is further journaled in a bearing 40 supported 50 by said frame 38. Mounted on the shaft 34 for rotation therewith, is a pinion 41 which meshes with a truck driving gear 42 loosely inounted on a vertical shaft 43 fixed in the casing 21 and framing 38. The gear 42 55 is formed with a hub 44 on which is mounted a sprocket 45 for driving the cutter chain 23, said sprocket being adapted to be clutched to said hub by means of suitable clutch mechanism indicated by the numeral 46. 60 Such clutch mechanism, being usual in machines of this type, requires no detailed description herein.

65 Loosely mounted on the shaft 34 is a clutch member 47 having an internal clutch face engaged by friction clutch members or

shoes 48 connected by toggle links 49 with a clutch controller 50 having a splined connection with the shaft 34. Movement of the controller 50 toward the member 47 causes the toggle links 49 to force the shoes 48 outwardly against the clutch face of the member 47, thereby frictionally connecting said member to the shaft 34. The controlling member 50 is normally pressed toward the clutch member 47 by means of a spring 51 bearing at one end against an interior shoulder on the member 50 and at its opposite end against a nut 52 on the threaded end of the shaft 34, whereby the tension of said spring may be adjusted. In the operation of the friction device last described, the member 47 is caused normally to rotate with the shaft 34, but is permitted to yield or slip on said shaft should an unusual resistance be encountered. - centric and having small and large gear portions 69 and 70 meshing, respectively, with a fixed internal gear 71 secured to the casing and a larger rotatable internal gear 72 secured to a flange 73 on a sleeve 74 to which said gear 68 is keyed or otherwise secured for rotation therewith. The gear 68 meshes with a gear 75 loosely mounted on a vertical shaft 76 secured at its ends in the casing 21, said gear 75 having a clutch face 77 adapted to be engaged by a cooperating clutch face on a sleeve 78 longitudinally and rotatably mounted on the shaft 76. The sleeve 78 is formed with a toothed portion constituting a pinion 79 which meshes with a gear 80 (see Figs. 2, 3, and 4), fast to the hub of the feed sprocket 28, which sprocket is rotatably mounted on the upright shaft 43.
- 20 By the connections above described, it will be seen that the feed sprocket 28 may be rotated in either direction to cause the feed chain 26 to feed the machine in either direction, according to the adjustment of the carrier 55 and the arrangement of said chain about the rollers or sprockets 27, 29, and 30, as above explained. In order to provide for an increased speed of rotation of the feed sprocket 28 and a corresponding- 25 ly increased rate of travel of the machine, the following transmission mechanism, operative alternatively with a portion of the mechanism last described, is provided:
- The sleeve 59, to which the gear 58 is keyed, constitutes the hub of a pinion 81 (see Figs. 4 and 6) which meshes with a gear 82 connected by mechanism presently to be described with a clutch member 83 having a clutch face 84 adapted to be en- 30 gaged by a cooperating clutch face on the end of the sleeve 78 opposite that engaging the clutch face 77 on the gear 75. By moving the sleeve 78 longitudinally to cause one or the other of the clutch faces on the ends 35 thereof to engage the clutch face 77 or the clutch face 84, the pinion 79, which drives the feed sprocket 28 through the gear 80, may be connected with either the gear 75 or the gear 82, thereby causing said feed 40 sprocket to be driven from the gear 58 either at a slow speed through the differential gearing 69, 70, etc., and gears 68 and 75, or at an increased speed through the pinion 81 and gear 82. In order that said 45 clutch sleeve 78 may be conveniently shifted, said sleeve is formed with a groove 85 engaged by studs on a fork 86 fast on a rock shaft 87 journaled in brackets secured to the casing 21, said rock shaft having fast 50 thereon an arm 88 connected by a link 89 to an eccentric pin 90 on a stud 91 rotatably mounted in the casing and provided with an operating handle 92. With the handle 92 in the position shown in Fig. 4, the mechanism 55 is adjusted to produce a slow feed of the apparatus, while by moving said handle 92 into a diametrically opposite position the gearing may be shifted to produce the fast feed.
- When the relatively fast feed is em- 70 ployed, the friction mechanism employed for yieldingly connecting the shaft 34 and pinion 53 may advantageously be adjusted to oppose an increased resistance against yielding or slipping of the parts than when the slow speed is employed, and for the purpose of conveniently providing for such increased resistance the following mechanism for loading the friction device is employed, reference being had particularly to Figs. 80 4 and 5.
- Rotatably mounted on the clutch controlling member 50, as by an anti-friction bearing 93, is a ring or collar 94 having trunnions to which are pivoted arms 95 on a rock shaft 96 journaled in suitable bearings on the casing 21 and having secured to its end a hand lever 97. The arms 95 are normally fixed to the shaft 96, being, for reasons hereinafter explained, preferably secured thereto by means permitting a slight angular adjustment of said arms on said shaft, said means comprising a hub 98 keyed to the shaft and carrying a rotatable stud 99 having eccentric end portions 100 engaging slots in extensions 101 on said arms whereby rotation of said pin, as by means of an implement inserted in one of the openings 102 therein, may be caused to produce a slight angular movement of said arms on said shaft. The pin 99 is normally held against rotation in the hub 98 by means of set screws 103.
- By lifting up on the hand lever 97, the arms 95 may be caused to press downwardly 105 upon the ring 94, thereby supplementing the action of the spring 51 and causing the shoes 48 to engage the clutch surface on the member 47 with an increased pressure. For purposes of safety, it is desirable that this loading of the friction be prevented when the mechanism is adjusted to produce a slow feed, and to this end an interlock is provided between the levers 92 and 97, said interlock comprising an extension 104 on the lever 97, which overlies an extended portion 105 of the lever 92, whereby when said lever 92 is in the position to adjust the transmission mechanism for a slow feed, as shown in Figs. 1, 4, and 8, said extension 105, by 110 engaging the extension 104, will prevent manipulation of the lever 97 to increase the friction.
- Similarly, it is desirable that means be 115 provided for preventing a change in the friction during the operation of shifting the reversing gearing, and to this end an interlock is also provided between the levers 97 and 64, said interlock comprising a lip 106 (see Figs. 4 and 9) on the lever 97 which is 120 125 130

engaged by a hooked lug 107 on the lever 64 except when said last named lever is in one of its extreme positions.

Here it will also be noted that thru the provision of the lip 106 and hooked lug 107, means are also provided to lock the lever 64 against movement prior to movement of the lever 97, the lip 106 normally being disposed in the same plane with the lug 107 in such a manner as to prevent movement of the lever 64 until the lever 97 is depressed into its friction releasing position shown in Fig. 9. Movement of the lever 64 to an intermediate position during the shifting of the reversing gearing causes the lug 107 to overlie the lip 106, thereby locking the lever 97 against operation. The arms 95 may be so angularly adjusted on the rock shaft 96, by the means heretofore referred to, as to secure such a positioning of the lever 97 as will permit the proper cooperation of the interlocking devices above described.

Since manipulation of the lever 97 causes an increase in the driving tension limited only by the strength of the operator, it is desirable that automatic releasing means be provided to insure the mechanism against breakage in case of overload, such means being preferably interposed between the gear 82 and sleeve 83 and forming transmission elements of the fast feed mechanism. Referring to Figs. 6, 10, and 11, the upper face of the gear 82 is formed with a circular recess, the annular wall of which is provided with notches 108 formed with inclined walls. Located in the recess in the gear 82 and keyed to the sleeve 83, is a disk 109 having recesses in which are slidably mounted a series of plungers 110 normally impelled outwardly by springs 111 located in said recesses behind said plungers. As shown in Fig. 10, said plungers are arranged in oppositely inclined pairs and are provided with ends formed substantially to fit the notches 108. The plungers of one pair are adapted positively but releasably to transmit motion from the gear 82 to the disk 109 when said gear is rotated in one direction, while the plungers of the other pair are adapted similarly to transmit motion from the gear to the disk when said gear is rotated in the opposite direction. Assuming the direction of rotation of the gear 82 to be as indicated by the arrow in Fig. 10, it will be seen that the direct thrust of the walls of the notches or recesses 108 against the ends of the plungers 110 designated by the letter *b*, will be such as to force said plungers inwardly against the tension of their springs 111, whereas the walls of the recesses 108 exert a wedging action upon the plungers designated by the letter *a*, permitting said plungers to remain in the operative position shown and provide a positive driving connection between the gear 82 and

disk 109. When, however, the pressure upon said plungers *a* becomes excessive, the cam action of the walls of the recesses upon the ends of said plungers will cause said plungers to be forced inwardly against the tension of their springs, thereby disconnecting the gear 82 and disk 109. Similarly, if the gear 82 be rotated in the opposite direction, the plungers *a* will become inoperative and the plungers *b* operative.

In order to permit the pressure exerted by the springs 111 upon the plungers 110 to be varied, said springs preferably engage followers 112 in threaded engagement with screws 113 abutting against the rear faces of said plungers, whereby rotation of said screws will permit said followers to be moved away from the rear faces of the plungers, thereby increasing the tension of the springs.

Instead of arranging the plungers 110 in oppositely inclined pairs, said plungers may be radially arranged and provided with oppositely inclined faces, as shown at 114 in Fig. 12. As in the construction first described, the plungers 114 are backed by springs 111 bearing against followers 112 carried by screws 113 abutting the inner faces of the plungers 114.

A further modification is shown in Fig. 13 wherein the plungers comprise balls 115 backed by followers 116 against which bear springs 117 the opposite ends of which act against followers 118 adjustably connected with the bottoms of the recesses 119 in the disk 109 by abutment screws 120.

It will be understood by those familiar with the art that, in the normal operation of the machine, as said machine is fed along the wall being cut, it is held by the feeding means in a position substantially at right angles to said wall, as indicated by dotted lines in Fig. 14. As the end of the cut is approached, however, it is desirable to swing or turn the machine from its normal position to cause the end of the cutter bar to cut to a point substantially in alignment with the rib, as indicated in full lines in Fig. 14, in order to produce a straight rib. A similar turning movement of the machine is also frequently desirable at other points in the travel thereof across the wall, as, for example, in cutting out an obstruction, or for other purposes. The present invention, therefore, comprises means whereby the feeding mechanism may be caused, at will, to swing or turn the machine out of its perpendicular position with respect to the wall as well as to propel the same along said wall. To this end, in the construction shown, means are provided for so connecting the feed chain 26 with the rear guide sprocket 27 as to prevent said sprocket from paying out said chain, i. e., to arrest relative movement of said sprocket and chain in a direc-

tion longitudinally of the latter, while continuing the feeding action of the feed sprocket 28 upon said chain and the movement of the latter with respect to the guide sprockets 29 and 30. As shown in Figs. 14 and 15, said means comprises a connecting member 125 having at its opposite ends hooks 126 and 127 adapted, respectively, to engage a convenient link of the chain 26 and a hub 128 on the sprocket 27. For convenience in use said hooks are preferably disposed in planes forming an angle of approximately 90° with each other, as shown in detail in Fig. 16. With the member 125 in place, as shown in Fig. 15 and in full lines in Fig. 14, as the feed sprocket 28 draws in upon the forward end of the chain 26, said chain, by engagement with the guide sprocket or roller 30, causes the forward end 10 of the machine to continue its advance, whereas the advance of the rear end of the machine is arrested by its connection with the rear end of the chain, so that said machine is turned from the position shown in dotted lines in Fig. 14 into the position shown in full lines therein.

In the use of my improved construction, it will be noted that the machine may cut laterally, with equal facility from right to left or from left to right, the operation being the same in each case and the only change necessary to permit reversal being the reversal of the motor and the cutter bits and the reversal of the flexible feeding means relative to the guides 29 and 30. Thus in either direction of cut the portion selected as the advance portion leads off from the front end of the advancing side of the machine, while the other portion which then acts as the receding portion extends laterally from the rear end of the receding side thereof, and all changing of the flexible portions relative to their feed operating means is made unnecessary. Inasmuch as a description of the summing cut at one rib and a transverse cut from that rib to the opposite rib will suffice for both, I will accordingly only describe in detail a summing cut at the right-hand rib, and the following transverse cut. In this connection it will be observed that as illustrated at the right in Fig. 14, it is possible, when the machine is unloaded at the face ready to make a cut from right to left, to connect the free end of the advance portion of the flexible feeding member to the left hand rib at A and to connect the free end of the receding portion of the flexible feeding member to the right hand rib as to a take-up at B and then, through suitable connection of my improved driving mechanism for the feed operating member 28, rotate the latter to draw in the receding portion at a predetermined slow or cutting speed at the same time that the cutter chain driving sprocket 45 is rotated in a counter-clockwise direction. As a result, the machine moves forward during summing relative to the flexible feeding means from the rearward dotted line position illustrated at the right of Fig. 14 toward the forward dotted line position illustrated in that figure. Then after suitably connecting the member 125 in such manner as to hold the rear end of the machine against movement away from the rib by limiting the lengthening of the receding portion, the machine is straightened in the cut, herein through swinging the bar end thereof angularly toward the left and through a longer path than the rear end as 75 the machine moves bodily forward, by simply reversing the direction of rotation of the feed operating member 28 through the improved reverse feeding mechanism and without changing the speed of the feed operating member or the speed or direction of rotation of the motor, the latter continuing to rotate at full speed and in the same direction. As a result of this reversal of the feed operating member to draw in the advance 80 portion and the use of the member 125 the machine is thus caused to occupy while near the rib the position relative to the face desired during the transverse cut herein illustrated in the central dotted line position of 85 Fig. 14. By then simply removing the member 125 and taking up the slack, the machine is free to move transversely as desired at a uniform and predetermined cutting speed, the machine being suitably balanced by the 90 action of the advancing and receding portions on its opposite ends. Thus, it will be observed that it is possible to sum the machine and move the same transversely across the face, with one setting of jacks where the 100 operator is skillful, and with the cutter chain always rotating in the same direction, and without stopping the motor or without reversing or varying the speed of the latter. Attention is also directed to the fact that a 105 predetermined cutting speed is obtainable during the summing operation which is herein the same as the cutting speed during a transverse cut, thereby enabling the machine to be summed in this direct manner 110 along the receding portion and moved transversely with only one setting of the jacks by a skillful operator even in the hardest cutting. Furthermore, it will be noted that at any time desired it is possible through 115 the fast and slow feeds in each direction, not only to cooperate with the member 125 to angle the machine at different speeds when desirable but also to pull either end of the machine forward or backward at either high or slow speed during transverse or angling cutting whether the member 125 is used or not. It will also be observed that through my improved construction wherein 120 these improved results may be obtained 125

either when cutting from right to left or from left to right, i. e., in either arrangement of the flexible feeding means relative to the machine, the advance flexible feeding portion in cutting from right to left becoming the receding flexible feeding portion in cutting from left to right, while the receding flexible feeding portion in cutting from right to left becomes the advance flexible feeding portion in cutting in the opposite direction and the machine being movable relative to the new flexible portions during sumping or transverse cutting as previously described in connection with cutting from left to right. Here it will also be noted that in this reverse arrangement of the flexible feeding portions, each individual portion in either of its arrangements extends laterally in the same direction, herein from the same side of the machine, although from opposite ends of the frame, thus eliminating all necessity for crossing the flexible feeding portions at the rear of the machine and simplifying the connections and guiding means necessary at the same time that the flexible feeding portions are caused to be shortened or lengthened in the desired sequence to expedite successive machine movements. It will further be noted that at the completion of a cut in either direction, the machine may be angled relative to the face as, for example, illustrated at the left hand side of Fig. 14, and that after it has completed the cut, i. e., backed out of the same at that angle, the machine may be returned to the truck at the opposite rib by simply fixing either desired end of the flexible feeding member usually the end of the receding portion at a point adjacent the truck and rotating the feed operating member 28 at high speed in such a direction as to propel the machine along the desired portion of the flexible feeding member.

As a result of my improved construction, it is found possible in cutting in either direction to reduce the number of jack settings where conditions are favorable, and under all conditions to reduce the requisite handling of the flexible feeding means and otherwise materially to reduce the time required during the cutting operations. Further, through the provision of my improved means whereby the machine may be moved relative to either receding portion at a predetermined cutting speed, it is also made possible at either rib to sump the machine smoothly and rapidly with this same simplified connection even in the hardest cutting with entire safety to the operator. Also, through the use of my improved means for limiting or inhibiting the paying out of one portion while still permitting drawing in of the other portion at different speeds, in this illustrative construction including the member 125 adapted to cooperate with

either receding portion, it is made possible to straighten the machine during sumping at either rib by a movement of the bar in the same direction which it takes during the transverse cut and thus further expedite the cutting operation, the only delay incident to the transition from the sumping cut to the transverse cut being that involved in connecting and disconnecting the member 125. Also it will be evident that this same means may be used in other relations where it is desirable for one portion to be drawn in while the other is retained of the same length, as, for example, when swinging the bar around to widen a room. Through the provision of the predetermined high speed feed operable to draw in either portion, it is also made possible to increase the speed of feed whenever conditions permit while the machine is working on the face, or whenever desired while moving over the mine bottom. It will also be noted that the manually releasable friction mechanism including the operating handle also makes it possible, by slipping the friction as needed, to decrease any of the geared feeds as desired during either cutting or moving whenever it is desirable to meet particular conditions. Further, it will be noted that this friction mechanism is automatically releasable to protect the machine whenever any feed is overloaded. Attention is here also directed to the fact that in my improved construction when sumping at one or either rib, the receding portion may whenever desired be passed around the front guide sprocket on the receding side of the machine (Fig. 17) before connecting it to the rib, thereby giving added control for the machine through minimizing the tendency of the rear end of the machine to swing against the rib and thus insuring a straighter sumping cut along the rib. It will also be evident that when sumping at one or either rib the advance portion may if desired be released from the front guide sprocket on the advancing side of the machine and lie directly in a relatively taut connection between the guide sprocket at the rear of that side and the jack at the rib so that it exerts a maximum balancing effect on the rear end of the machine as the latter moves toward the face as the receding portion is drawn in and the advance portion lengthened, Fig. 17, this arrangement or the arrangement of the advance portion shown in Fig. 14 being used with the receding portion in either of its arrangements previously described, depending upon the conditions encountered. For example, when desired the arrangement may be as shown in Fig. 18 wherein both portions engage their front guides initially. Attention is also directed to Fig. 19 wherein it will be noted that the rib is being finished or squared by drawing in the advance

125 130

portion to pull the machine back out of the face, and the advance jack or anchor then being moved backward along the rib and the receding jack released, as indicated. In all 5 of the arrangements shown, it will also be observed that this jack A may be placed in position for the transverse cut before the sumping cut, or starting cut, is made and remain there from the beginning of the 10 sumping cut to the end of the transverse cutting operation. It will also be observed that the anchor B may remain in position whenever the receding portion is not passed around its front guide, provided the 15 position is skillfully selected. As shown in Fig. 20 it is also possible for the machine to cut from left to right when arranged reversely from the manner shown in Fig. 14. In connection with this it should also be noted 20 that in either right or left hand cutting the sumping or rib finishing arrangements shown in the preceding figures may be used if desired. These and other advantages of 25 my improved construction will however be clearly apparent to those skilled in the art.

While I have in this application specifically described one form which my invention may assume in practice, it will be noted that this form of the same has been 30 used for purposes of illustration and that my invention or certain features thereof may be modified and embodied in various other forms without departing from its spirit or the scope of the appended claims.

What I claim as new and desire to secure 35 by Letters Patent is:

1. A room and pillar mining machine 40 slideable on the mine bottom comprising a frame, cutting mechanism thereon including a cutter bar projecting from said frame in fixed longitudinal relation thereto and carrying a rotatable cutter chain provided with elements circulating in orbits extending longitudinally of said bar and operative 45 to cut and clear kerfs, flexible feeding means operative to effect feeding movement and to determine the angular relation of said machine to a working face during the various cutting operations and including advance 50 and receding portions disposable laterally in opposite directions from the opposite ends of said frame, and feed operating and cutter chain driving means including a motor having a power shaft disposed longitudinally of said frame and means actuatable 55 by the rear end of said power shaft and disposed wholly to the rear of the front end of said motor and operative to effect circulation of said cutter chain and to wind in 60 said advance portion and unwind said receding portion to feed said machine at a predetermined low speed across a face as said cutter chain is rotated in one direction, said means having provision for winding in 65 said receding portion at a like predetermined

speed and at another speed, both without reversing the direction of said cutter chain or motor or alteration in the mode of operative connection between said receding portion of said winding means existing during 70 said feed across the face.

2. A room and pillar mining machine 75 slideable on the mine bottom comprising a frame, a motor thereon constituting a source of power for cutting and feeding mechanism actuation, cutting mechanism on said frame including a cutter bar projecting from said frame in fixed longitudinal relation thereto and carrying a rotatable cutter chain provided with elements operative to 80 cut and clear kerfs and circulating in plane substantially horizontal orbits, flexible feeding means operative to effect feeding movement and to determine the angular relation of said machine to a working face during the various cutting operations and including advance and receding portions disposable laterally in opposite directions from the 85 opposite ends of said frame, and feed operating and cutter chain driving means driven from the same end of said motor and operative to wind in the advancing portion and unwind the receding portion to feed said machine at a predetermined low speed across 90 a face as said cutter chain is rotated by said motor in one direction, said means having provision for winding in said receding portion at the same predetermined speed and also at a faster speed substantially in excess 95 of the maximum potential cutting speed of said machine under normal working conditions, both without reversing the direction of said cutter chain or motor or alteration in the mode of operative connection between 100 said receding portion and said winding means existing during said feed across the face.

3. A room and pillar mining machine 110 slideable on the mine bottom comprising a frame, a motor thereon constituting a source of power for cutting and feeding mechanism, cutting mechanism on said frame including a plane cutter bar projecting from said frame in fixed longitudinal relation thereto and carrying for circulation about its edge in a horizontal orbit a rotatable cutter chain, flexible feeding means operative to effect feeding movement and to determine the angular relation of said machine 115 to a working face during the various cutting operations and including advance and receding portions disposable laterally in opposite directions from the opposite ends of said frame, and feed operating and cutter chain driving means driven from the same end of 120 said motor and operative to wind in said advancing portion and unwind said receding portion to feed said machine at a predetermined low cutting speed across a face as 125 said cutter chain is rotated by said motor

- in one direction, said means having provision for winding in said receding portion at the same predetermined speed and also a predetermined faster speed substantially in excess of the maximum potential cutting speed of said machine under normal working conditions both without reversing the direction of said cutter chain or motor or alteration in the mode of operative connection between said receding portion and said winding means existing during said feed across the face. 70
4. A mining machine slidable on a mine bottom comprising a frame; cutting mechanism thereon including a cutter bar carrying a rotatable cutter chain, flexible motor in said frame having a longitudinally extending armature shaft, feeding means including advance and receding portions disposable laterally in opposite directions from the opposite ends of said frame, and feed operating and cutter chain driving means operative to wind in said advance and unwind said receding portion to feed said machine at a predetermined low speed across a face as said cutter chain is rotated in one direction, said means having provision for winding in said receding portion without reversing the direction of said cutter chain and said feed operating means including an epicyclic gearing through which power may be transmitted to effect winding in of both the advance and receding portions. 75
5. A mining machine slidable on a mine bottom comprising a frame, cutting mechanism thereon including a rotatable cutter chain, flexible feeding means including advance and receding portions disposable laterally in opposite directions from the opposite ends of said frame, and feed operating and cutter chain driving means operative to wind in said advance and unwind said receding portion to feed said machine at a predetermined low speed across the face as said cutter chain is rotated in one direction, said means having provision for winding in said receding portion at a like predetermined speed without reversing the direction of said cutter chain and said feed operating means including an epicyclic gearing through which power may be transmitted to effect winding in of both the advance and receding portions. 80
6. In a mining machine, a machine frame, flexible feeding means thereon including advance and receding flexible feeding portions, feed operating means including a feed operating member acting on said receding portion, a motor on said frame, and variable speed driving connections driven by said motor and operable to rotate said feed operating member including an epicyclic gearing comprising orbitally moving coaxial gears meshing respectively with a reaction gear and a gear driven by the orbitally moving gear which meshes therewith, said variable speed gearing being selectively operable to drive said feed operating member at different predetermined speeds to shorten said receding portion. 85
7. In a mining machine, a machine frame, flexible feeding means thereon including advance and receding flexible feeding portions, feed operating means including a feed operating member acting on said receding portion, a motor on said frame, and variable speed driving connections driven by said motor and operable to rotate said feed operating member including a differential gearing comprising orbitally moving coaxial gears meshing respectively with a reaction gear and with a gear driven by the orbitally moving gear which meshes therewith, said variable speed gearing being selectively operable to drive said feed operating member at different predetermined speeds to wind in said receding portion and a friction device disposed in said variable speed driving mechanism. 90
8. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame, at all times during cutting, flexible feeding means including advance and receding portions disposable laterally in opposite directions from the opposite ends of said frame and when so extended controlling the angular relation of the frame to a working face, and feed operating and cutter chain driving means including a motor having a longitudinally-extending power shaft and mechanism driven wholly from one end thereof, operative to feed said machine in one direction relative to said advance portion at a plurality of speeds while said cutter chain rotates in a single direction including a predetermined cutting feed and a faster feed or in an opposite direction and relative to said receding portion at a plurality of speeds including a like predetermined cutting speed and a faster speed. 95
9. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame, at all times during cutting flexible feeding means including advance and receding portions disposable laterally in opposite directions from the opposite ends of said frame and when so extended controlling the angular relation of the frame to a working face. 100
10. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame, at all times during cutting flexible feeding means including advance and receding portions disposable laterally in opposite directions from the opposite ends of said frame and when so extended controlling the angular relation of the frame to a working face. 105
11. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame, at all times during cutting flexible feeding means including advance and receding portions disposable laterally in opposite directions from the opposite ends of said frame and when so extended controlling the angular relation of the frame to a working face. 110
12. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame, at all times during cutting flexible feeding means including advance and receding portions disposable laterally in opposite directions from the opposite ends of said frame and when so extended controlling the angular relation of the frame to a working face. 115
13. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame, at all times during cutting flexible feeding means including advance and receding portions disposable laterally in opposite directions from the opposite ends of said frame and when so extended controlling the angular relation of the frame to a working face. 120
14. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame, at all times during cutting flexible feeding means including advance and receding portions disposable laterally in opposite directions from the opposite ends of said frame and when so extended controlling the angular relation of the frame to a working face. 125
15. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame, at all times during cutting flexible feeding means including advance and receding portions disposable laterally in opposite directions from the opposite ends of said frame and when so extended controlling the angular relation of the frame to a working face. 130

- face, and feed operating and cutter chain driving means including a motor having a longitudinally extending power shaft and mechanism driven wholly from one end thereof operative to feed said machine in one direction relative to said advance portion at a plurality of speeds including a predetermined cutting feed and a faster feed or in an opposite direction and relative to said receding portion at a plurality of speeds including a like predetermined cutting speed and a predetermined faster speed without reversing the direction of rotation of said cutter chain.
15. 10. A mining machine slidable on the mine bottom comprising a frame, cutting mechanism thereon including a cutter bar projecting from said frame in fixed longitudinal relation thereto and carrying a rotatable cutter chain provided with elements operative to cut and clear kerfs and moving in orbits extending longitudinally of said frame at all times during cutting, flexible feeding means including advance and receding portions disposable laterally in opposite directions from the opposite ends of said frame and when so extended controlling the angular relation of the frame to a working face, means for disposing said feeding portions for right or left hand feeding, and feed operating and cutter chain driving means including a motor having a longitudinally extending power shaft and means connectible with the rear end of the latter and operative to feed said machine along either receding portion at a predetermined low speed while said cutter chain is rotated in one direction and thereafter to feed said machine along either advance portion at the same speed while paying out its receding portion and continuing to drive said cutter chain in the same direction.
11. The combination with a mining machine including a frame slidable on a mine bottom and having a rigid longitudinally projecting cutter chain carrying cutter bar, a motor having a longitudinally extending power shaft, and driving connections between the rear end of said shaft and said cutter chain, of means for feeding said machine including flexible feeding portions extending from the opposite sides of said frame and feeding operating mechanism wholly actuatable by the rear end of said motor power shaft and operative to draw in either one of said portions at a plurality of predetermined speeds without reversal of said motor or alteration in the mode of immediate cooperation between said feed operating mechanism and said portions, said mechanism also having provision for drawing in one of said portions at a predetermined speed while permitting lengthening of the other at substantially the same speed.
- 65 12. The combination with a mining machine including a frame slidable on a mine bottom and having a rigid longitudinally projecting cutter bar provided with orbitally moving cutting elements traversing their orbits oppositely during the cutting of kerfs in opposite directions, of means for feeding said machine bodily laterally in either direction to effect kerf cutting in either direction including flexible feeding portions in either relation extending from the opposite ends of said frame and determining its angular relation to the face, and feed operating mechanism operative in either relation to draw in one of said portions at a predetermined speed while permitting lengthening of the other at substantially the same speed, said mechanism including a longitudinally disposed motor having driving connections only with its rear end and said mechanism also having provision for drawing in either one of said portions at a plurality of predetermined speeds without reversal of said motor or alteration in the immediate cooperation of said feed operating mechanism with such portions between such several drawings in.
13. A room and pillar mining machine slidable on the mine bottom comprising a frame, cutting mechanism thereon including a rotatable cutter chain whose orbit at all times is disposed longitudinally of the frame, a continuous flexible feeding member on said machine disposable laterally in opposite directions in advance and receding portions from the opposite ends of said frame, and feed operating and cutter chain driving means operative to wind in said advance portion and unwind said receding portion to feed said machine at a predetermined low speed across a face as said cutter chain is rotated in one direction, said means including a longitudinally arranged motor with but one end of which power connections are provided and said means having provision for winding in either of said portions at a plurality of predetermined speeds without reversing the direction of said cutter chain or alteration in the immediate cooperation of the feed operating means with said portions.
14. A room and pillar mining machine slidable on the mine bottom comprising a frame, cutting mechanism thereon including a cutter bar rigidly projecting from said frame longitudinally of the latter and carrying a rotatable cutter chain traversing an elongated orbit whose major dimension is, throughout cutting, disposed longitudinally of the machine, a continuous flexible feeding member on said machine disposable laterally in opposite directions in advance and receding portions from the opposite ends of said frame, and feed operating and cutter chain driving means including a friction controlling device operative to feed

- said machine in one direction relative to said advance portion at a plurality of speeds or in an opposite direction and relative to said receding portion at a plurality of speeds 5 without varying the load on said friction device or reversal of the direction of cutter chain drive.
15. A room and pillar mining machine slidable on the mine bottom comprising a frame, cutting mechanism thereon including a permanently longitudinally extending cutter bar carrying a rotatable cutter chain, a continuous flexible feeding member on said frame including advance and receding portions disposable laterally in opposite directions from the opposite ends of said frame and controlling its angular relation to a working face, means for disposing said feeding portions for right or left hand 10 feeding, and feed operating and cutter chain driving means operative to feed said machine along either receding portion at a predetermined low speed while said cutter chain is rotated in one direction and there- 15 after to feed said machine along either advance portion at the same speed while paying out its receding portion and continuing to drive said cutter chain in the same direction as during the preceding feed along 20 the receding portion.
16. A mining machine slidable on a mine bottom comprising a frame, cutting mechanism thereon including a projecting cutter bar disposed longitudinally of said frame 25 throughout the cutting operations and a rotatable cutter chain on said bar, flexible feeding and guiding means for feeding said bar to make a lateral cut in a face in either direction including advance and receding 30 portions disposable during lateral cutting in one direction laterally in opposite directions from the opposite ends of said frame and having provision whereby said portions may be respectively reversely arranged as 35 receding and advance portions during lateral cutting in the opposite direction, and feed operating said controlling and cutter chain driving means operative during lateral cutting in either direction to wind in the ad- 40 vancing portion at a predetermined cutting speed and permit lengthening of the reced- 45 ing portion to feed said machine across a face as said cutter chain is rotated in one direction, said last mentioned means also having provision for at will winding in the receding portion at a predetermined cutting speed while said cutter chain rotates in the 50 same direction as during the lateral cutting 55 operation or winding in said portion at a faster speed.
17. A mining machine slidable on a mine bottom comprising a frame, cutting mechanism thereon including a projecting cutter bar disposed longitudinally of said frame throughout the cutting operations and a rotatable cutter chain on said bar, flexible 60 feeding and guiding means for feeding said bar to make a lateral cut in a face in either direction including advance and receding portions disposable during lateral cutting in one direction laterally in opposite directions from the opposite ends of said frame and 65
- feeding and guiding means for feeding said bar to make a lateral cut in a face in either direction including advance and receding portions disposable during lateral cutting in one direction laterally in opposite directions 70 from the opposite ends of said frame and having provision whereby said portions may be respectively reversely arranged as receding and advancing portions during lateral cutting in the opposite direction, and feed operating and controlling and cutter chain driving means operative during lateral cutting in either direction to wind in the advance portion at a predetermined cutting speed and permit lengthening of the receding portion to feed said machine across a face as said cutter chain is rotated in one direction, said last mentioned means also having provision for at will winding in the receding portion at a predetermined cutting speed while said cutter chain rotates in the same direction as during the lateral cutting 80 operation or winding in said portion at a faster speed.
18. A mining machine slidable on a mine bottom comprising a frame, cutting mechanism thereon including a projecting cutter bar disposed longitudinally of said frame throughout the cutting operations and a rotatable cutter chain on said bar, flexible feeding and guiding means for feeding said bar to make a lateral cut in a face in either direction including advance and receding portions disposable during lateral cutting in one direction laterally in opposite directions 85 from the opposite ends of said frame and having provision whereby said portions may be respectively reversely disposed as receding and advancing portions during lateral cutting in the opposite direction, and feed operating and controlling and cutter chain driving means operative during lateral cutting in either direction to wind in the advancing portion at a predetermined cutting speed and permit lengthening of the receding portion to feed said machine across a face as said cutter chain is rotated in one direction, said last mentioned means also having provision for at will winding in the receding portion at a predetermined cutting speed while said cutter chain rotates in the same direction as during the lateral cutting 90 operation or winding in said portion at a faster speed.
19. A mining machine slidable on a mine bottom comprising a frame, cutting mechanism thereon including a projecting cutter bar disposed longitudinally of said frame throughout the cutting operations and a rotatable cutter chain on said bar, flexible feeding and guiding means for feeding said bar to make a lateral cut in a face in either direction including advance and receding portions disposable during lateral cutting in one direction laterally in opposite directions 95 from the opposite ends of said frame and

- having provision whereby said portions may be respectively reversely disposed as receding and advancing portions during lateral cutting in the opposite direction, and feed 5 operating and controlling and cutter chain driving means operative during lateral cutting in either direction to wind in the advancing portion at a predetermined cutting speed and permit lengthening of the receding portion to feed said machine across the face as said cutter chain is rotated in one direction, said last mentioned means also having provision for at will winding in said receding portion at a like predetermined cutting speed without interrupting or reversing the direction 70 of said cutter chain and also including differential reduction gearing whereby said winding in speed may be changed.
- 10 20. A mining machine slidable on a mine bottom comprising a frame, cutting mechanism thereon including a projecting cutter bar disposed longitudinally of said frame throughout the cutting operations and a rotatable cutter chain on said bar, flexible feeding and guiding means for feeding said bar to make a lateral cut in a face in either direction including advance and receding portions disposable during lateral cutting in either direction laterally in opposite directions from the opposite ends of said frame and having provision whereby during sumping at either rib the portion subsequently forming the receding portion may be disposed substantially longitudinally of the receding side of the machine, and feed operating and controlling and cutter chain driving means operative during lateral cutting in either direction to wind in the advance portion at a predetermined cutting speed and permit lengthening of the receding portion to feed said machine across a face as said cutter chain is rotated in one direction, said last mentioned means also having provision for at will winding in the receding portion without interrupting or reversing the direction of said cutter chain and also including gearing whereby said winding in speed may be changed.
- 15 25 30 35 40 45 50 55 60 65 70 75 80 85 90 95 100 105 110 115 120 125 130 21. A mining machine slidable on a mine bottom comprising a frame, cutting mechanism thereon including a projecting cutter bar disposed longitudinally of said frame throughout the cutting operations and a rotatable cutter chain on said bar, flexible feeding and guiding means for feeding said bar to make a lateral cut in a face in either direction including advance and receding portions disposable during lateral cutting in one direction laterally in opposite directions from the opposite ends of said frame and having provision whereby said portions may be respectively disposed as receding and advancing portions during lateral cutting in the opposite direction, and feed operating and controlling and cutter chain driving means operative during lateral cutting in either direction to wind in the advance portion at a predetermined cutting speed and permit lengthening of the receding portion to feed said machine across the face as said cutter chain is rotated in one direction, said last mentioned means also having provision for at will winding in said receding portion at a like predetermined cutting speed without interrupting or reversing the direction of said cutter chain and also including differential reduction gearing whereby said winding in speed may be changed.
22. In a mining machine, a machine frame slidable on a mine bottom, cutting mechanism thereon including a projecting cutter bar disposed longitudinally of said frame throughout cutting and rigidly connected thereto, flexible feeding and guiding means on said frame for feeding said bar to make a lateral cut in a face in either direction including advance and receding flexible feeding portions disposable during lateral cutting in one direction laterally in opposite directions from opposite ends of said frame and having provision whereby said advancing and receding portions may be respectively reversely arranged as receding and advance portions, feed operating and controlling means operative to shorten and permit lengthening of the advance and receding portions respectively during lateral cutting in either direction including a feed operating member acting on said receding portion when the latter is disposed as either a receding or advance portion, a motor on said frame for driving said cutting mechanism and said feed operating means, and variable speed driving connections driven by said motor and operable at will to rotate said feed operating member to draw in said receding portion in either disposition thereof including differential reduction gearing and selectively operable to drive said feed operating member at different speeds.
23. In a mining machine, a machine frame slidable on a mine bottom, cutting mechanism thereon including a projecting cutter bar disposed longitudinally of said frame during lateral cutting and rigidly connected thereto, flexible feeding and guiding means on said frame for feeding said bar to make a lateral cut in a face in either direction including advance and receding flexible feeding portions disposable during cutting in one direction laterally in opposite directions from opposite ends of said frame and having provision whereby said advance and receding portions may be respectively reversely disposed as receding and advance portions during cutting in the opposite direction, and feed operating and controlling means operative to shorten and permit lengthening of the advance and receding portions respectively during lateral cutting

- in either direction including a feed operating member acting on said receding portion when the latter is disposed as either a receding or advance portion, a motor on said frame for driving said cutting mechanism and said feed operating means, and variable speed driving connections driven by said motor and operable at will to rotate said feed operating member to draw in said receding portion in either disposition thereof including differential reduction gearing and selectively operable to drive said feed operating member at different speeds and friction mechanism further controlling the rotation of said feed operating member.
24. A mining machine slidable on a mine bottom comprising a frame, cutting mechanism thereon including a projecting cutter bar disposed longitudinally of said frame and rigidly connected thereto throughout the cutting operations and a rotatable cutter chain on said bar, flexible feeding and guiding means for feeding said bar to make a lateral cut in a face in either direction including advance and receding portions disposable during transverse cutting from right to left laterally in opposite directions from the opposite ends of said frame and having provision whereby said advance and receding portions may be respectively reversely disposed as receding and advance portions during cutting from left to right or with a receding portion extending substantially longitudinally of the machine during sumping at either rib, and feed operating and controlling and cutter chain driving means operative during sumping at either rib to feed said machine along the receding portion at a predetermined cutting speed while said cutter chain is rotated in one direction and thereafter during lateral cutting to feed said machine along the advance portion at a predetermined cutting speed while permitting lengthening of said receding portion to maintain the opposite ends of said machine in substantially balanced relation and continuing to drive said cutter chain in the same direction.
25. A mining machine slidable on a mine bottom comprising a frame, cutting mechanism thereon including a projecting cutter bar disposed longitudinally of said frame and rigidly connected thereto throughout the cutting operations and a rotatable cutter chain on said bar, flexible feeding and guiding means for feeding said bar to make a lateral cut in a face in either direction including advance and receding portions disposable during lateral cutting in one direction laterally in opposite directions from the opposite ends of said frame and having provision whereby said portions may be reversely disposed respectively as receding and advance portions during lateral cutting in
- the opposite direction, and feed operating and controlling and cutter chain driving means operative in either disposition of said portions and without interrupting the drive of or reversing said cutter chain to feed said machine laterally along the face and relative to said portions during lateral cutting and also having provision whereby said frame may be fed at will in one direction relative to the advance portion at a plurality of speeds including a predetermined cutting feed and a faster feed or in an opposite direction and relative to the receding portion at a plurality of speeds including a like predetermined cutting feed and a faster feed.
26. A mining machine slidable on a mine bottom comprising a frame, cutting mechanism thereon including a projecting cutter bar disposed longitudinally of said frame and rigidly connected thereto throughout the cutting operations and a rotatable cutter chain on said bar, flexible feeding and guiding means for feeding said bar to make a lateral cut in a face in either direction including advance and receding portions disposable during lateral cutting in one direction laterally in opposite directions from the opposite ends of said frame and having provision whereby said portions may be reversely disposed respectively as receding and advance portions during lateral cutting in the opposite direction, and feed operating and controlling and cutter chain driving means operative in either disposition of said portions and without reversing or interrupting the drive of said cutter chain to feed said machine laterally along a face and relative to said portions during lateral cutting and also having provision whereby said frame may be fed at will in one direction relative to the advance portion at a plurality of speeds including a predetermined cutting feed and a faster feed or in an opposite direction and relative to the receding portion at a plurality of speeds including a like predetermined cutting feed and a predetermined faster feed.
27. A mining machine slidable on a mine bottom comprising a frame, cutting mechanism thereon including a projecting cutter bar disposed longitudinally of said frame and rigidly connected thereto throughout the cutting operations and a rotatable cutter chain on said bar, flexible feeding and guiding means for feeding said bar to make a lateral cut in either direction along a face including advance and receding portions disposable during lateral cutting in one direction laterally in opposite directions from the opposite ends of said frame, means for reversely disposing said feeding portions respectively as receding and advance portions for lateral cutting in the opposite direction including mechanism whereby each may be extended in the same direction as before but

from the opposite end of said frame, and feed operating and controlling and cutter chain driving means operative to feed said machine along either receding portion at a predetermined low speed while said cutter chain is rotated in one direction and thereafter to feed said machine along the advance portion at a suitable cutting speed while paying out the receding portion and continuing to drive said cutter chain in the same direction.

28. The combination with a mining machine including a frame slidable on a mine bottom and having during sumping and lateral cutting a rigid longitudinally disposed and projecting cutter chain carrying cutter bar, of means for feeding said machine over a mine bottom and guiding said bar into and in either direction laterally along a mine face including flexible feeding portions extending from the opposite sides of said frame, guiding means for operatively disposing either of said portions longitudinally of its side of said frame or laterally in the same direction from opposite ends thereof, and feed operating and controlling mechanism operative to draw in either one of said portions without reversing or interrupting the drive of said cutter chain, said mechanism also having provision for drawing in either of said portions at a predetermined speed while permitting lengthening of the other at substantially the same speed in such manner as to hold the opposite ends of the machine in substantially balanced relation during lateral cutting in opposite directions and while drawing in different portions.

29. The combination with a mining machine including a frame slidable on a mine bottom and having throughout cutting a rigid longitudinally disposed and projecting cutter chain carrying cutter bar, of means for feeding said machine bodily laterally along a face in either direction including flexible feeding portions and cooperating mechanism whereby during cutting in either direction said portions extend in opposite directions from opposite ends of said frame and yet in each direction of cut each individual portion extends in the same direction from the same side of said frame, and feed operating and controlling mechanism operative in either relation to draw in one of said portions at a predetermined speed while permitting lengthening of the other at substantially the same speed in such manner as to hold the opposite ends of the machine in substantially balanced relation during lateral cutting, said mechanism also having provision for at will drawing in either one of said portions at a plurality of predetermined speeds.

30. A mining machine slidable on a mine bottom comprising a frame, cutting mecha-

nism thereon including a projecting cutter bar disposed longitudinally of said frame throughout cutting and rigidly connected thereto and a rotatable cutter chain on said bar, a continuous flexible feeding member on said machine, means for disposing said member for lateral feeding in either direction with advance and receding portions disposed laterally in opposite directions from the opposite ends of said frame, means for operatively disposing the receding portion at either rib substantially longitudinally of the receding side of said machine during sumping, and feed operating and controlling and cutter chain driving means operative in either relation of said portions to wind in the advance portion and permit lengthening of the receding portion to feed said machine at a predetermined low speed across a face as said cutter chain is rotated in one direction, said last mentioned means also having provision for at will winding in the receding portion at a like speed without reversing the direction of said cutter chain.

31. A mining machine slidable on a mine bottom comprising a frame, cutting mechanism thereon including a projecting cutter bar disposed longitudinally of said frame throughout cutting and rigidly connected thereto and a rotatable cutter chain on said bar, a continuous flexible feeding member on said machine disposable laterally in opposite directions in advance and receding portions from the opposite ends of said frame, means for disposing said member for reverse lateral feeding with said receding portion the advance portion and said advance portion the receding portion, and feed operating and controlling and cutter chain driving means operative in either relation of said portions to wind in said advance portion and permit lengthening of said receding portion to feed said machine at a predetermined low speed across a face as said cutter chain is rotated in one direction, said means having provision for winding in one of said portions at a plurality of speeds without reversing the direction of said cutter chain.

32. A mining machine slidable on a mine bottom comprising a frame, cutting mechanism thereon including a projecting cutter bar disposed longitudinally of said frame throughout cutting and rigidly connected thereto and a rotatable cutter chain on said bar, a continuous flexible feeding member on said machine disposable during lateral feeding in one direction laterally in opposite directions in advance and receding portions from the opposite ends of said frame, means for disposing said member for reverse lateral feeding with said receding portion the advance portion and with said advance portion the receding portion, and feed operating and controlling and cutter chain

driving means operative in either relation of said portions to feed said machine along the receding portion during sumping at a cutting speed and thereafter during lateral cutting to feed said machine along the advance portion at a like cutting speed while paying out said receding portion to maintain the opposite ends of said machine in substantially balanced relation and continuing to drive said cutter chain in the same direction, said last mentioned means also having provision for winding in either of said portions at will at a higher speed.

33. A mining machine slidable on a mine bottom comprising a frame, cutting mechanism thereon including a projecting cutter bar disposed longitudinally of said frame throughout cutting and rigidly connected thereto and a rotatable cutter chain on said bar, a continuous flexible feeding member on said machine disposable laterally in opposite directions in advance and receding portions from the opposite ends of said frame, means for disposing said member for reverse lateral feeding with said receding portion the advance portion and with said advance portion the receding portion, and feed operating and controlling and cutter chain driving means including a friction controlling device and operative to feed said machine in one direction relative to the advance portion at a plurality of speeds or in an opposite direction and relative to the receding portion at a plurality of speeds with the same load on said friction device and without stopping or reversal of the direction of cutter chain drive.

34. A mining machine slidable on a mine bottom comprising a frame, cutting mechanism thereon including a projecting cutter bar disposed longitudinally of said frame throughout cutting and rigidly connected thereto and a rotatable cutter chain on said bar, a continuous flexible feeding member on said frame including advance and receding portions disposable laterally in opposite directions from the opposite ends of said frame, means for disposing said feeding portions for right or left hand feeding, and feed operating and controlling and cutter chain driving means operative to feed said machine along either receding portion at a predetermined low speed while said cutter chain is rotated in one direction and thereafter to feed said machine along the advance portion at the same speed while paying out the receding portion and continuing to drive said cutter chain in the same direction.

35. The combination with a mining machine, of feeding mechanism including a friction device, reversing mechanism, variable speed mechanism, controlling members for said device and each of said mechanisms, and interlocking connections between said members.

36. The combination with a mining machine, of feeding mechanism including friction mechanism, reversing mechanism, variable speed mechanism, controlling members for each of said members, and interlocking connections between one of said members and each of the others. 70

37. The combination with a mining machine, of feeding mechanism including a friction device and reversing mechanism, controlling members for each of the same including a controlling member for said reversing mechanism disposable in different positions during reverse operations, and interlocking connections between said friction 75 and reverse controlling members effective in a plurality of said positions of said reverse controlling member.

38. The combination with a mining machine, of feeding mechanism including a friction device and reversing mechanism, controlling members for each of said members including a controlling member for said reversing member disposable in different positions during reverse operations, and means operative in a plurality of said positions of said reverse controlling member for inhibiting the operation of said reverse controlling member prior to movement of said friction controlling member to releasing 95 position.

39. The combination with a mining machine, of feeding mechanism including a friction device and reversing mechanism, controlling members for each of the same 100 including a controlling member for said reversing mechanism disposable in different positions during reverse operations and means operative in opposite positions of said controlling member for inhibiting loading of said friction controlling member until said reverse controlling member occupies a predetermined position.

40. The combination with a mining machine, of a feed operating member and driving mechanism therefor including a frictional controlling mechanism and reversing mechanism, and controlling connections therefor operative in opposite positions of said reverse controlling member before and after said reversing mechanism to remove the load from said mechanism before reversal thereof and to apply the load thereto after the reversal thereof. 110

41. In a mining machine, the combination 115 with feeding means, of mechanism for actuating said feeding means including a frictional controlling mechanism and a supplemental mechanism having two coaxially arranged members, one of said members having recesses, and the other of said members having means normally engaging said recesses but automatically detachable therefrom under conditions of overload. 125

42. In a mining machine, the combination 130

- with feeding means, of mechanism for actuating said feeding means including a frictional controlling mechanism and a supplemental mechanism having two coaxially arranged members, one of said members having recesses formed with inclined walls, and the other of said members having means normally engaging said recesses but automatically displaceable therefrom under conditions of overload. 50. In a mining machine, the combination with feeding means, of mechanism for actuating said feeding means including a frictional controlling mechanism and a supplemental mechanism having two coaxially arranged members, one within the other, the outer member having recesses formed with inclined walls, and the inner member having means normally engaging said recesses but automatically displaceable therefrom under conditions of overload. 51. In a mining machine, the combination with feeding means, of mechanism for actuating said feeding means including a frictional controlling mechanism and a supplemental mechanism having two coaxially arranged members, one of said members having recesses, and the other of said members having spring pressed plungers formed with inclined portions engaging said recesses. 52. In a mining machine, the combination with feeding means, of mechanism for actuating said feeding means including a frictional controlling mechanism and a supplemental mechanism having two coaxially arranged members, one of said members having recesses, and the other of said members having spring pressed plungers engaging said recesses, said plungers being arranged in oppositely inclined pairs. 53. In a mining machine, the combination with feeding means, of mechanism for actuating said feeding means including a yielding element and a supplemental transmission connection per se independent of manual control automatically released by conditions of overload. 54. In a mining machine, the combination with feeding means, of mechanism for actuating said feeding means including a yielding element, means for increasing the resistance to yielding opposed by said element, and an additional transmission connection per se independent of manual control automatically released by conditions of overload. 55. The combination with a mining machine, of feeding mechanism therefor in
- with feeding means including a frictional controlling mechanism and a supplemental mechanism having two coaxially arranged members, one of said members having recesses formed with inclined walls, and the other of said members having means normally engaging said recesses but automatically displaceable therefrom under conditions of overload. 50. In a mining machine, the combination with feeding means, of mechanism for actuating said feeding means including a frictional controlling mechanism and a supplemental mechanism having two coaxially arranged members, one within the other, the outer member having recesses formed with inclined walls, and the inner member having means normally engaging said recesses but automatically displaceable therefrom under conditions of overload. 51. In a mining machine, the combination with feeding means, of mechanism for actuating said feeding means including a frictional controlling mechanism and a supplemental mechanism having two coaxially arranged members, one of said members having recesses, and the other of said members having spring pressed plungers formed with inclined portions engaging said recesses. 52. In a mining machine, the combination with feeding means, of mechanism for actuating said feeding means including a frictional controlling mechanism and a supplemental mechanism having two coaxially arranged members, one of said members having recesses, and the other of said members having spring pressed plungers engaging said recesses, said plungers being arranged in oppositely inclined pairs. 53. In a mining machine, the combination with feeding means, of mechanism for actuating said feeding means including a yielding element and a supplemental transmission connection per se independent of manual control automatically released by conditions of overload. 54. In a mining machine, the combination with feeding means, of mechanism for actuating said feeding means including a yielding element, means for increasing the resistance to yielding opposed by said element, and an additional transmission connection per se independent of manual control automatically released by conditions of overload. 55. The combination with a mining machine, of feeding mechanism therefor in

cluding a feed operating member and a flexible feeding member cooperating therewith and having a single strand extending laterally from the receding side of said machine, and means on said machine for limiting the paying out of said strand adapted to grip the latter.

56. The combination with a mining machine having cutting mechanism including a longitudinally projecting cutter chain carrying cutter bar and cutting elements circulating in substantially horizontal plane orbits, which bar projects longitudinally of the machine during both sumping and cutting across a face of feeding mechanism including flexible feeding portions adapted to act on opposite sides of said machine and each adapted to act as an advance and as a receding portion depending on the direction in which a kerf is to be cut across a face, and feed operating and controlling mechanism operative to draw in either portion at a predetermined cutting speed, including means on said machine for checking the paying out of either portion while drawing in the other, said machine including a motor rotatable in opposite directions during the cutting of oppositely extending kerfs.

57. The combination with a mining machine having cutting mechanism including a longitudinally projecting cutter chain carrying cutter bar and cutting elements circulating in substantially horizontal plane orbits, which bar projects longitudinally of the machine during both sumping and cutting across a face of feeding mechanism therefor including a continuous flexible feeding member cooperating therewith and having single strands extending from the opposite sides of said machine and each adapted to act as an advance and as a receding portion depending on the direction in which a kerf is to be cut across a face, and feed operating and controlling means operative to draw in either strand at a predetermined cutting speed, and including adjustable means on said machine for limiting the paying out of either of said strands while permitting drawing in of the other, said machine including a motor rotatable in opposite directions during the cutting of oppositely extending kerfs.

58. The combination with a mining machine, of feeding mechanism therefor including a feed operating member and a cooperating flexible feeding member having single strands extending in opposite directions from opposite ends of said machine, and means on said machine gripping one of said strands at different points in its length to limit the paying out of said strand.

59. In a mining machine, in combination, a rotary feed member adjacent the rear of said machine, a rotary guide member located

in the rear of said feed member, a pair of guide members at each side of said machine, a flexible feeding member passing about said feed member and said first named guide member and engageable with either pair of said last named guide members to cause said machine to move in either direction, and means for securing said flexible feeding member to said first named guide member.

60. In a mining machine, the combination of a guide sprocket, a feed sprocket, a feed chain passing about said sprockets, and means for securing said chain to said guide sprocket.

61. In a mining machine, the combination of a guide member, a rotary feed member, a flexible feeding member cooperating with said guide member and said rotary feed member, and a connecting member having opposite hooked ends adapted respectively to engage said guide member and said flexible feeding member.

62. In a mining machine, the combination of a guide sprocket having a hub, a feed sprocket, a feed chain passing about said sprockets, and a connecting member having opposite hooked ends adapted respectively to engage said chain and hub.

63. In a mining machine, the combination of a guide sprocket having a hub, a feed sprocket, a feed chain passing about said sprockets, and a connecting member having opposite hooked ends lying in angularly disposed planes and adapted respectively to engage said chain and hub.

64. In a mining machine, the combination of a feed sprocket, a guide sprocket having a hub, said guide sprocket being located in the rear of said feed sprocket, a feed chain passing about said sprockets, and a connecting member having opposite hooked ends lying in angularly disposed planes and adapted, respectively, to engage said chain and hub.

65. In a mining machine, reversible variable speed friction controlled feeding mechanism including a reversing lever, a speed controlling lever, and a friction controlling lever, said reversing lever and said friction controlling lever being movable in intersecting planes, and said speed controlling lever being movable in a plane parallel to the plane of movement of one of said levers.

66. In a mining machine, reversible variable speed friction controlled feeding mechanism including a reversing lever, a speed controlling lever, and a friction controlling lever, said reversing lever and said friction controlling lever being movable in intersecting planes, and said speed controlling lever being movable in a plane parallel to the plane of movement of said reverse controlling lever.

67. In a mining machine, reversible variable speed friction controlled feeding mecha-

- nism including a reversing lever, a speed controlling lever, and a friction controlling lever, said reversing lever and said friction controlling lever being movable in intersecting planes, and said speed controlling lever being movable in a plane parallel to the plane of movement of said reverse controlling lever and into the path of said friction controlling lever.
- 10 68. In a mining machine, reversible variable speed friction controlled feeding mechanism including a reversing lever, a speed controlling lever, and a friction controlling lever, said reversing lever and said friction controlling lever being movable in intersecting planes, and said speed controlling lever being movable in a plane parallel to the plane of movement of said reverse controlling lever and into the path of said friction controlling lever, and interlocking connections between said friction controlling lever and said reverse lever.
- 15 69. In a mining machine, feeding mechanism including a feed operating member, a friction device, and variable speed reversible gearing intermediate said members, a reverse controlling lever, a friction controlling lever, a speed controlling lever, and interlocking connections between said levers operative to prevent manual loading of said friction device during slow feed or operation of the friction lever during reversing.
- 20 70. In a mining machine, feeding mechanism including a feed operating member, a friction device, and variable speed reversible gearing intermediate said members, a reverse controlling lever, a friction controlling lever, a speed controlling lever, and interlocking connections between said levers operative to prevent loading of said friction device during slow feed or operation of the friction lever during reversing, said connections inhibiting reversal prior to disconnection of said friction.
- 25 71. In a mining machine, feeding mechanism comprising a friction device, a feed operating member, and variable speed reduction gearing between the same including a movable reversing gear, a friction controlling member, a reverse controlling member, and means inhibiting operation of the friction controlling member during movement of said movable reversing gear.
- 30 72. In a mining machine, feeding mechanism including a feed operating member and driving gearing therefor including a plurality of yielding devices, one of said devices being subject to manual control and the other being located between said last mentioned device and said feed operating member and releasable automatically when subjected to a predetermined load irrespective of the amount of loading of said manually controlled device.
- 35 73. In a mining machine, feeding mech-
- anism including a feed operating member, and driving gearing therefor including a plurality of yielding devices, one of said devices being subject to manual control and the other being independent of manual control and automatically releasable on overload irrespective of the amount of loading of said manually controlled device, said last mentioned device being arranged nearer said feed operating member in the drive for the latter than said first mentioned device.
- 40 74. In a mining machine, a feed operating member, variable speed gearing driving the same comprising gears rotatable on a plurality of spaced fixed axes, and a plurality of manually meshing gears rotatable on movable axes movable bodily about one of said fixed axes, a motor, driving connections between the same and a gear on said last mentioned axis, and frictional means disposed in said gearing between said movable gears and said motor.
- 45 75. In a mining machine, a feed operating member, variable speed gearing driving the same comprising gears rotatable on a plurality of spaced fixed axes, and a plurality of gears rotatable on movable axes movable bodily about one of said fixed axes, a motor, driving connections between the same and a gear on said last mentioned axis, frictional means disposed in said gearing between said movable gears and said motor, and yielding means between said movable gears and said feed operating member.
- 50 76. In a mining machine, a feed operating member, variable speed reversible gearing driving the same comprising gears rotatable on fixed axes and a plurality of gears rotatable on movable axes, a motor, a friction device between the same and one of the gears rotatable on fixed axes, and variable speed clutch connections between the other of the gears rotatable on fixed axes and said feed operating member.
- 55 77. In a mining machine, a feed operating member, variable speed reversible gearing driving the same comprising gears rotatable on fixed axes and a plurality of movable gears rotatable on movable axes, a motor, a friction device between the same and one of the gears rotatable on fixed axes, variable speed clutch connections between the other of the gears rotatable on fixed axes and said feed operating member, separate controlling members for said friction device, said movable gears and said clutch, and interlocking connections between said members.
- 60 78. In a mining machine, a feed operating member, variable speed reversible gearing driving the same comprising gears rotatable on fixed axes and a plurality of movable gears rotatable on movable axes, a motor, a friction device between the same and one of the gears rotatable on fixed axes, variable

speed clutch connections between the other of the gears rotatable on fixed axes and said feed operating member, separate controlling members for said friction device, said movable gears and said clutch, interlocking connections between said friction controlling member and the movable gear controlling member, and interlocking connections between the friction controlling member and the clutch controlling member.

79. In a mining machine, a feed operating member, friction controlled reversible variable speed driving mechanism therefor including a friction controlling member, a reverse controlling member, and a speed controlling member, means whereby said friction and speed controlling members interengage in one position, and means whereby said friction and reverse controlling members 20 interengage in one position.

80. In a mining machine, a feed operating member, friction controlled reversible variable speed driving mechanism therefor including a friction controlling member, a reverse controlling member, and a speed controlling member, means whereby said friction speed controlling members interengage in one position, means whereby said friction and reverse controlling members 30 interengage in one position, and separate latch mechanism for said reverse and friction controlling members.

81. In a mining machine, a machine frame, a feed operating member thereon and a cutter chain driving sprocket thereon disposed on parallel axes in different horizontal planes, said frame including a horizontal septum between said feed operating member and sprocket, a motor on said frame, driving 40 connections between the same and said feed operating member disposed above said septum, driving connections for said cutter chain sprocket operatively connected to said driving connections and disposed below said 45 septum including a truck driving gear beneath said septum and concentric with said sprocket and adapted to engage an element on a truck.

82. In a mining machine, a machine frame, 50 a feed operating member thereon disposed on a vertical axis, a horizontal motor on said frame, and driving mechanism for said feed operating member driven by said motor comprising variable speed mechanism driven by said motor and including an epicyclic reduction gearing, each element of said variable speed mechanism being rotatable in a horizontal plane.

83. The combination with a mining machine having a frame slidable on a mine bottom and reversible cutting mechanism including a cutter chain carrying cutter bar disposed longitudinally of said frame throughout the cutting operations, of flexible 65 feeding and guiding mechanism having pro-

vision for at will guiding said cutter bar into a face at either rib and bodily laterally along the face away from either rib including in either right or left hand cutting a flexible feeding portion adapted to form 70 the advance portion and a flexible feeding portion disposable substantially longitudinally of the receding side of said machine as a summing member during summing or acting laterally on the rear end of the machine frame as a receding member during lateral cutting, and mechanism on said machine operative at will without reversing or interrupting the drive of said cutting mechanism to draw in said last mentioned 80 portion at a predetermined cutting speed or to draw in the advance portion at a predetermined cutting speed while permitting said last mentioned portion to be lengthened.

84. The combination with a mining machine having a frame slidable on a mine bottom and reversible cutting mechanism including a cutter chain carrying cutter bar disposed longitudinally of said frame throughout its cutting operations, of flexible feeding and guiding mechanism having provision for at will guiding said cutter bar into a face at either rib and bodily laterally along the face away from either rib including in either right or left hand cutting a 90 flexible feeding portion adapted to form the advance portion and a flexible feeding portion disposable substantially longitudinally of the receding side of said machine as a summing member during summing or laterally from the rear end or interruption of drive of the machine as a receding member during lateral cutting, and mechanism on said machine operative at will without reversal of said cutting mechanism to draw in 95 said last mentioned portion at a predetermined cutting speed or at a predetermined higher speed or to draw in the other portion at a predetermined cutting speed during lateral cutting while permitting said last mentioned portion to be lengthened.

85. The combination with a mining machine having a frame slidable on a mine bottom and reversible cutting mechanism including a cutter chain carrying cutter bar 115 disposed longitudinally of said frame throughout its cutting operations, of flexible feeding and guiding mechanism having provision for at will guiding said cutter bar into a face at either rib and bodily laterally along the face away from either rib including in either right or left hand cutting a flexible feeding member adapted to form an advance portion and a flexible feeding portion disposable substantially longitudinally 120 of the receding side of said machine as a summing member during summing or laterally from the rear end of the machine as a receding member during lateral cutting, and mechanism on said machine operative 125 130

- at will without reversal of said cutting mechanism or interruption of the drive thereof to draw in said last mentioned portion at a predetermined cutting speed, a predetermined higher speed, or at speeds slower than said speeds or to draw in the other portion at a predetermined cutting speed while permitting said last mentioned portion to be lengthened.
86. The combination with a mining machine having a frame slideable on a mine bottom and reversible cutting mechanism including a cutter chain carrying cutter bar disposed longitudinally of said frame throughout its cutting operations, of flexible feeding and guiding mechanism having provision for at will guiding said cutter bar into a face at either rib and bodily laterally along the face away from either rib including in either right or left hand cutting a flexible feed portion adapted to form an advance portion and a flexible feeding portion disposable substantially longitudinally of the receding side of said machine as a sumping member during sumping or acting laterally on the rear end of the machine frame as a receding member during lateral cutting, and mechanism on said machine for at will drawing in said last mentioned portion at a predetermined cutting speed or drawing in the other portion at a predetermined cutting speed while permitting said last mentioned portion to be lengthened, likewise including means on said machine having provision for controlling the effective length of said last mentioned portion while permitting the drawing in of the other portion at different speeds.
87. The combination with a mining machine having a frame slideable on a mine bottom and reversible cutting mechanism including a cutter chain carrying cutter bar disposed longitudinally of said frame throughout the cutting operations, of flexible feeding and guiding mechanism having provision for at will guiding said cutter bar into a face at either rib and bodily laterally along the face away from either rib including in either right or left hand cutting a flexible feeding portion adapted to form an advance portion and a flexible feeding portion disposable substantially longitudinally of the receding side of said machine as a sumping member during sumping or laterally from the rear end of the machine as a receding member during lateral cutting, and mechanism on said machine for at will drawing in said last mentioned portion at any one of a plurality of speeds including a predetermined cutting speed or drawing in the other portion at any one of a plurality of speeds including a predetermined cutting speed while permitting said last mentioned portion to be lengthened, said mechanism including means on said machine adjustable to control lengthening of one portion while still permitting drawing in of the other portion.
88. The combination with a mining machine having a frame slideable on a mine bottom and reversible cutting mechanism including a cutter chain carrying cutter bar disposed longitudinally of said frame throughout its cutting operations, of flexible feeding and guiding mechanism having provision for at will guiding said cutter bar
- bottom and reversible cutting mechanism including a cutter chain carrying cutter bar disposed longitudinally of said frame throughout its cutting operations, of flexible feeding and guiding mechanism having provision for at will guiding said cutter bar into a face at either rib and bodily laterally along the face away from either rib including in either right or left hand cutting a flexible feeding portion adapted to form an advance portion and a flexible feeding portion disposable substantially longitudinally of the receding side of said machine as a sumping member during sumping or acting laterally on the rear end of the machine frame as a receding member during lateral cutting, and mechanism on said machine for at will drawing in said last mentioned portion at a predetermined cutting speed or drawing in the other portion at a predetermined cutting speed while permitting said last mentioned portion to be lengthened, likewise including means on said machine having provision for controlling the effective length of said last mentioned portion while permitting the drawing in of the other portion at different speeds.
89. The combination with a mining machine having a frame slideable on a mine bottom and reversible cutting mechanism including a cutter chain carrying cutter bar disposed longitudinally of said frame throughout its cutting operations, of flexible feeding and guiding mechanism having provision for at will guiding said cutter bar into a face at either rib and bodily laterally along the face away from either rib including in either right or left hand cutting a flexible feeding portion adapted to form an advance portion and a flexible feeding portion disposable substantially longitudinally of the receding side of said machine as a sumping member during sumping or laterally from the rear end of the machine as a receding member during lateral cutting, and mechanism on said machine for at will drawing in said last mentioned portion at any one of a plurality of speeds including a predetermined cutting speed or drawing in the other portion at any one of a plurality of speeds including a predetermined cutting speed while permitting said last mentioned portion to be lengthened, said mechanism including means on said machine adjustable to control lengthening of one portion while still permitting drawing in of the other portion.
90. The combination with a mining machine having a frame slideable on a mine bottom and reversible cutting mechanism including a cutter chain carrying cutter bar disposed longitudinally of said frame throughout its cutting operations, of flexible feeding and guiding mechanism having provision for at will guiding said cutter bar

into a face at either rib and bodily laterally along the face away from either rib including in either right or left hand cutting a flexible feeding portion adapted to form the 5 advance portion and a flexible feeding portion disposable substantially longitudinally of the receding side of said machine as a sumping member during sumping or laterally from the rear end of the machine as a receding member during lateral cutting, and mechanism on said machine for at will drawing in said last mentioned portion or either portion at a predetermined cutting speed or at a predetermined higher speed or 10 drawing in said first mentioned portion at a predetermined cutting speed during lateral cutting while permitting said last mentioned portion to be lengthened, said mechanism including means on said machine adjustable at 15 will to control the lengthening of one portion while still permitting drawing in of the other.

91. The combination with a mining machine having a frame slidable on a mine bottom and reversible cutting mechanism including a cutter chain carrying cutter bar disposed longitudinally of said frame throughout its cutting operations, of flexible feeding and guiding mechanism having provision for at will guiding said cutter bar into a face at either rib and bodily laterally along the face away from either rib including in either right or left hand cutting a flexible feeding member adapted to form the 25 advance member and a flexible portion disposable substantially longitudinally of the receding side of said machine as a sumping member during sumping or laterally from the rear end of the machine as a receding member during lateral cutting, and mechanism on said machine for at will drawing in said last mentioned portion at a predetermined cutting speed or drawing in the other portion at a predetermined cutting speed while permitting said last mentioned portion to be paid out, said mechanism including means for at will drawing in one of said portions at a slower speed and means on said machine adjustable at will 30 to control the lengthening of one portion while permitting the other to be drawn in.

92. The combination with a mining machine having a frame slidable on a mine bottom and reversible cutting mechanism including a cutter chain carrying cutter bar disposed longitudinally of said frame throughout its cutting operations, of flexible feeding and guiding mechanism having a continuous flexible feeding member and having provision for at will guiding said cutter bar into a face at either rib and bodily laterally along the face away from either rib and including in either right or left hand cutting a flexible feeding portion 35 adapted to form the advance portion and

a flexible feeding portion disposable substantially longitudinally of the receding side of said machine as a sumping member during sumping or laterally from the rear end of the machine as a receding member during 70 lateral cutting, and mechanism on said machine for at will drawing in said last mentioned portion at a sumping speed or at a higher speed or drawing in the other portion at a predetermined transverse cutting speed while permitting said last mentioned portion to be lengthened, said mechanism including means on said machine adjustable at will to control the lengthening of one portion while permitting drawing in of the 75 other portion.

93. The combination with a mining machine having a frame slidable on a mine bottom and reversible cutting mechanism including a cutter chain carrying cutter bar 80 disposed longitudinally of said frame throughout its cutting operations, of flexible feeding and guiding mechanism having a continuous flexible feeding member and having provision for at will guiding said cutter bar into a face at either rib and bodily laterally along the face away from either rib including in either right or left hand cutting a flexible feeding portion adapted to form the advance portion and a flexible portion 85 disposable substantially longitudinally of the receding side of said machine as a sumping member or laterally from the rear end of the machine as a receding member, and mechanism on said machine for at will drawing in said last mentioned portion at a predetermined cutting speed or at a higher speed or drawing in the other portion at any of a plurality of speeds including a predetermined cutting speed while permitting said last mentioned portion to be lengthened, said mechanism including means on said machine adjustable at will to control the lengthening of one portion while still permitting the drawing in of the other portion 90 at different speeds.

94. A mining machine slidable on a mine bottom comprising a frame, a motor disposed longitudinally thereof, cutting mechanism driven by the rear end of said motor 100 including a cutter carrying cutter bar disposed longitudinally of said machine throughout the sumping and lateral cutting operations, and mechanism for sumping said bar into and thereafter feeding it laterally along a face including a plurality of flexible feeding portions adapted to form advance and receding portions, means for disposing said receding portion as a sumping portion substantially longitudinally of the receding side of said machine or during lateral cutting disposing said advance portion longitudinally of the advancing side of the machine frame and laterally therefrom and said receding portion reversely laterally, and wind- 105 110 115 120 125 130

ing means driven by the rear end of said motor and operative to effect sumping and lateral feeding, said winding means including connections for drawing in either portion at a predetermined cutting speed without reversing said cutting mechanism or interrupting its operation.

95. A mining machine slidable on a mine bottom comprising a frame, a motor disposed longitudinally thereof, cutting mechanism driven by the rear end of said motor including a cutter carrying cutter bar disposed longitudinally of said machine throughout the sumping and lateral cutting operations, and mechanism for sumping said bar into and thereafter feeding it laterally along a face including a plurality of flexible feeding portions adapted to form advance and receding portions, means for disposing said receding portion as a sumping portion substantially longitudinally of the receding side of said machine or during lateral cutting disposing said advance portion longitudinally of the advancing side of the machine frame and laterally therefrom and said receding portion reversely laterally, and winding means driven by the rear end of said motor and operative to effect sumping and lateral feeding, said winding means including connections for drawing in either portion at a predetermined cutting speed without reversing or interrupting drive of said cutting mechanism or for drawing in one portion at a higher speed.
96. A mining machine slidable on a mine bottom comprising a frame, a motor disposed longitudinally thereof, cutting mechanism driven by the rear end of said motor including a cutter carrying cutter bar disposed longitudinally of said machine throughout the sumping and lateral cutting operations, and mechanism for sumping said bar into and thereafter feeding it laterally along a face including a plurality of flexible feeding portions adapted to form advance and receding portions, means for disposing said receding portion as a sumping portion substantially longitudinally of the receding side of said machine or during lateral cutting disposing said advance portion longitudinally of the advancing side of the machine frame and laterally therefrom and said receding portion reversely laterally, and winding means driven by the rear end of said motor and operative to effect sumping and lateral feeding, said winding means including connections for drawing in either portion at a predetermined cutting speed without reversing or interrupting drive of said cutting mechanism or for drawing in either portion at a higher speed.

97. A mining machine slidable on a mine bottom comprising a motor having a power shaft disposed longitudinally of the machine, cutting mechanism driven thereby in-

cluding a cutter carrying cutter bar disposed longitudinally of said machine throughout the sumping and lateral cutting operations, and mechanism for sumping said bar into and thereafter feeding it laterally along a face with said cutting mechanism operating in the same direction as during the sumping operation including a plurality of flexible feeding portions each having a free extremity and one adapted to form the advance portion and the other the receding portion, means for disposing the advance portion laterally from the advancing side of the machine during lateral cutting and the receding portion substantially longitudinally along or laterally relative to the receding side thereof during sumping or lateral cutting respectively, and winding means for said portions driven entirely from one end of said motor, said winding means including mechanism driven by said motor and operative without reversal of the latter to draw in either portion at a predetermined cutting speed or at a predetermined higher speed.

98. A mining machine slidable on a mine bottom comprising a motor, cutting mechanism driven thereby including a cutter carrying cutter bar disposed longitudinally of said machine throughout the sumping and lateral cutting operations, and mechanism for sumping said bar into and thereafter feeding it laterally along a face with said cutting mechanism operating in the same direction as during the sumping operation including a plurality of flexible feeding portions each having a free extremity and one adapted to form the advance portion and the other the receding portion, means for disposing the advance portion laterally from the advancing side of the machine during lateral cutting and the receding portion substantially longitudinally along or laterally relative to the receding side thereof during sumping or lateral cutting respectively, and winding means for said portions driven by said motor, said winding means including mechanism driven by said motor and operative without reversal of the latter or alteration in the mode of operative connection between said winding means and said portions to draw in one portion at a predetermined cutting speed or at a predetermined higher speed, or to draw in the other portion at the same speeds.

99. A mining machine slidable on a mine bottom comprising a motor, cutting mechanism driven thereby including a cutter carrying cutter bar disposed longitudinally of said machine throughout the sumping and lateral cutting operations, and mechanism for sumping said bar into and thereafter feeding it laterally along a face with said cutting mechanism rotating in the same direction as during the sumping operation including a plurality of flexible feeding por-

- tions each having a free extremity and one adapted to form the advance portion and the other the receding portion, means for disposing the advance portion laterally from the advancing side of the machine during lateral cutting and the receding portion substantially longitudinally along or laterally relative to the receding side thereof during sumping or lateral cutting respectively, and winding means for said portions, said winding means including a fast feed gear train and a slow feed gear train selectively driven by said motor and means for drawing in either of said portions through said slow feed gear train or one of the same through said fast feed gear train.
100. A mining machine slidable on a mine bottom comprising a motor, cutting mechanism driven thereby including a cutter carrying cutter bar disposed longitudinally of said machine throughout the sumping and lateral cutting operations, and mechanism for sumping said bar into and thereafter feeding it laterally along a face with said cutting mechanism operating in the same direction as during the sumping operation including a plurality of flexible feeding portions each having a free extremity and one adapted to form the advance portion and the other the receding portion, means for disposing the advance portion laterally from the advancing side of the machine during lateral cutting and the receding portion substantially longitudinally along or laterally relative to the receding side thereof during sumping or lateral cutting respectively, and winding means for said portions, said winding means including a fast feed gear train and a slow feed gear train selectively driven by said motor and means for drawing in either portion through either train without reversing the motor or altering the mode of operative connection between said winding means and said portions.
101. A mining machine slidable on a mine bottom comprising a motor, cutting mechanism driven thereby including a cutter carrying cutter bar disposed longitudinally of said machine throughout the sumping and lateral cutting operations, and mechanism for sumping said bar into and thereafter feeding it laterally along a face with said cutting mechanism operating in the same direction as during the sumping operation including a plurality of flexible feeding portions each having a free extremity and one adapted to form the advance portion and the other the receding portion, means for disposing the advance portion laterally from the advancing side of the machine during lateral cutting and the receding portion substantially longitudinally along or laterally relative to the receding side thereof during sumping or lateral cutting respectively, and winding means for said portions, said winding means including a slow feed gear train and a fast feed gear train selectively connectible to said motor, automatically releasable friction mechanism in either train, and means for drawing in either portion through said slow feed gear train.
102. A mining machine slidable on a mine bottom comprising a motor, cutting mechanism driven thereby including a cutter carrying cutter bar disposed longitudinally of said machine throughout the sumping and lateral cutting operations, and mechanism for sumping said bar into and thereafter feeding it laterally along a face with said cutting mechanism operating in the same direction as during the sumping operation including a plurality of flexible feeding portions each having a free extremity and one adapted to form the advance portion and the other the receding portion, means for disposing the advance portion laterally from the advancing side of the machine during lateral cutting and the receding portion substantially longitudinally along or laterally relative to the receding side thereof during sumping or lateral cutting respectively, and winding means for said portions, said winding means including slow speed gearing and fast speed gearing connectible selectively to said motor, automatically releasable friction mechanism in either train, and means for drawing in either portion through said slow feed gear train without reversing the motor or either of the same through said fast feed gear train.
103. A mining machine slidable on a mine bottom comprising a motor, cutting mechanism driven thereby including a cutter carrying cutter bar disposed longitudinally of said machine throughout the sumping and lateral cutting operations, and mechanism for sumping said bar into and thereafter feeding it laterally along a face with said cutting mechanism operating in the same direction as during the sumping operation including a plurality of flexible feeding portions each having a free extremity and one adapted to form the advance portion and the other the receding portion, means for disposing the advance portion laterally from the advancing side of the machine during lateral cutting and the receding portion substantially longitudinally along or laterally relative to the receding side thereof during sumping or lateral cutting respectively, and winding means for said portions, said winding means including a slow feed gear train and a fast feed gear train selectively connectible to said motor, automatically releasable friction mechanism in either train, and means for drawing in either portion through said slow feed gear train.

feed gear train without reversing the motor or one portion through said fast gear train including adjustable mechanism controlling each feed and freely releasable manually to 6 reduce either geared feed.

104. A mining machine slidable on a mine bottom comprising a motor, cutting mechanism driven thereby including a cutter carrying cutter bar disposed longitudinally of 10 said machine throughout the sumping and lateral cutting operations, and mechanism for sumping said bar into and thereafter feeding it laterally along a face with said cutting mechanism operating in the same 15 direction as during the sumping operation including a plurality of flexible feeding portions each having a free extremity and one adapted to form the advance portion and the other the receding portion, means 20 for disposing the advance portion laterally from the advancing side of the machine during lateral cutting and the receding portion substantially longitudinally along or laterally relative to the receding side there- 25 of during sumping or lateral cutting respectively, and winding means for said portions driven by said motor, said winding means including a slow feed gear train and a fast feed gear train connectible 30 selectively to said motor, automatically releasable friction mechanism in either train, and means for drawing in either portion through said slow feed gear train without reversing the motor or one portion 35 through said fast gear train including a single adjustable device controlling each feed and freely releasable manually to reduce either geared feed.

105. A mining machine slidable relative 40 to a mine bottom comprising a motor having a power shaft disposed longitudinally of the machine, cutting mechanism operatively connected to the rear end thereof and including a cutter carrying cutter bar disposed long- 45itudinally of said machine throughout the sumping and lateral cutting operations, and means for feeding said bar into and laterally along a face including a plurality of flexible feeding portions each having a free 50 extremity, means for disposing one portion substantially longitudinally of the receding side of the machine during sumping and both portions in opposite directions laterally from the opposite ends of the machine 55 during lateral cutting, winding means for said portions disposed to the rear of the front end of said motor, and operative transmission connections between said winding means and one end of said motor oper- 60 ative to effect sumping and lateral feeding and to draw in either portion at a predetermined cutting speed without interrupting the drive of or reversing said cutting mechanism or one portion at a higher speed, 65 said connections including variable speed

gearing and cooperating mechanism for selectively drawing in the desired portion at the desired geared speed through said variable speed gearing.

106. A mining machine slidable relative 70 to a mine bottom comprising a motor having a power shaft disposed longitudinally of the machine, cutting mechanism operatively connected to the rear end thereof and including a cutter carrying cutter bar disposed longitudinally of said machine throughout the sumping and lateral cutting operations, and means for feeding said bar into and laterally along a face including a plurality of flexible feeding portions each 75 having a free extremity, means for disposing one portion substantially longitudinally of the receding side of the machine during sumping and both portions in opposite directions laterally from the opposite ends of the machine during lateral cutting, winding means for said portions disposed to the rear of the front end of said motor, and operative transmission connections between said winding means and the rear end of said 80 motor operative to effect sumping and lateral feeding and to draw in either portion at a predetermined cutting speed without reversing or interrupting the drive of said cutting mechanism or one portion at a 85 higher speed, said connections including variable speed gearing, frictional mechanism automatically releasable upon overload of any feed, and cooperating mechanism for selectively drawing in the desired portion 90 at the desired geared speed through said variable speed gearing.

107. A mining machine slidable relative 95 to a mine bottom comprising a motor having a power shaft disposed longitudinally of the machine, cutting mechanism operatively connected thereto and including a cutter carrying cutter bar disposed longitudinally of said machine throughout the sumping and lateral cutting operations, and means 100 for feeding said bar into and laterally along a face including a plurality of flexible feeding portions each having a free extremity, means for disposing one portion substantially longitudinally of the receding side of the machine during sumping and both portions in opposite directions laterally from the opposite ends of the machine during 105 lateral cutting, winding means for said portions disposed to the rear of the front end of said motor, and operative transmission connections between said winding means and the rear end of said motor operative to 110 effect sumping and lateral feeding and to draw in either portion at a predetermined cutting speed without necessity for stopping or reversing said cutting mechanism or one portion at a higher speed, said connections including variable speed gearing, frictional mechanism automatically releasable upon 115

overload of any feed, adjustable connections for selecting the portion to be drawn in operative selectively to effect the drawing in of different portions through the same gearing, and adjustable connections for selecting the speed.

108. A mining machine slidable relative to a mine bottom comprising a motor having a power shaft disposed longitudinally of the machine, cutting mechanism operatively connected to the rear end thereof and including a cutter carrying cutter bar disposed longitudinally of said machine throughout the sumping and lateral cutting operations, and means for feeding said bar into and laterally along a face including a plurality of flexible feeding portions each having a free extremity, means for disposing one portion substantially longitudinally of the receding side of the machine during sumping and both portions in opposite directions laterally from the opposite ends of the machine during lateral cutting, winding means for said portions disposed to the rear of the front end of said motor, and operative transmission connections between said winding means and one end of said motor operative to effect sumping and lateral feeding and to draw in either portion at a predetermined cutting speed without interruption in the drive of or reversal of said cutting mechanism or alteration in the mode of immediate cooperation between said flexible portions and said winding means or one portion at a higher speed, said connections including variable speed gearing, adjustable connections for selecting the portion to be drawn in operative selectively to effect the drawing in of different portions through the same gearing, adjustable connections for selecting the speed, and frictional means releasable on overload of any feed, said frictional means common to all feeds and being manually controllable to reduce the geared feeds at will.

110. A mining machine slidable relative to a mine bottom comprising a motor having a power shaft disposed longitudinally of the machine, cutting mechanism operatively connected to the rear end thereof and including a cutter carrying cutter bar disposed longitudinally of said machine throughout the sumping and lateral cutting operations, and means for feeding said bar into and laterally along a face including a plurality of flexible feeding portions each having a free extremity, means for disposing one portion substantially longitudinally of the receding side of the machine during sumping and both portions in opposite directions laterally from the opposite ends of the machine frame during lateral cutting, winding means for said portions disposed to the rear of the front end of said motor, and operative transmission connections between said winding means and one end of said motor operative without change in the mode of immediate connection between said winding means and said flexible portions or reversal or interruption of the drive of said cutting mechanism to draw in either portion at any of a plurality of predetermined speeds including a predetermined slow or cutting speed and a predetermined higher speed in excess of the cutting capacity of the machine under normal working conditions.

109. A mining machine slidable relative to a mine bottom comprising a motor having a power shaft disposed longitudinally of the machine, cutting mechanism operatively connected to the rear end thereof and including a cutter carrying cutter bar disposed longitudinally of said machine throughout the sumping and lateral cutting operations, and means for feeding said bar into and laterally along a face including a plurality of flexible feeding portions each having a free extremity, means for disposing one portion substantially longitudinally of the receding side of the machine during sumping and both portions in opposite directions laterally from the opposite ends of the machine frame during lateral cutting, winding means for said portions disposed to the rear of the front end of said motor, and operative transmission connections between said winding means and one end of said motor operative to effect sumping and lateral feeding and to draw in either portion at a predetermined cutting speed without interruption in the drive of or reversing said cutting mechanism or alteration in the mode of immediate cooperation between said flexible portions and said winding means or one portion at a higher speed, said connections including variable speed gearing, adjustable connections for selecting the portion to be drawn in operative selectively to effect the drawing in of different portions through the same gearing, adjustable connections for selecting the speed, and frictional means releasable on overload of any feed, said frictional means common to all feeds and being manually controllable to reduce the geared feeds at will.

111. A mining machine slidable relative to a mine bottom comprising a motor, cutting mechanism operatively connected thereto and including a cutter carrying cutter bar disposed longitudinally of said machine throughout the sumping and lateral cutting operations, and means for feeding said bar into and laterally along a face including a plurality of flexible feeding portions each having a free extremity, means for disposing one portion substantially longitudinally of the receding side of the machine during sumping and both portions in opposite directions laterally from the opposite ends of the machine frame during lateral cutting, winding means for said portions, and operative transmission connections between said winding means and said

- motor operative without reversal or necessity for interrupting the drive of said cutting mechanism to draw in said sumping portion at a predetermined high speed in excess of the cutting capacity of the machine under normal conditions or at a predetermined slower speed or the other portion at a predetermined slow speed while permitting lengthening of said first mentioned portion.
- 10 112. A mining machine slidable on a mine bottom comprising cutting mechanism adapted to be driven in either direction including a motor and an operatively connected cutter carrying cutter bar disposed longitudinally of said machine throughout the sumping and lateral cutting operations, and mechanism for sumping said bar into a face at either rib and thereafter feeding it laterally away from the selected rib with said cutting mechanism operating in the same direction as during sumping, said mechanism including a plurality of flexible feeding portions each having a free extremity, means for enabling at different ribs disposal of a different portion substantially longitudinally of the receding side of the machine during sumping and thereafter laterally as a receding portion during lateral cutting and for enabling disposal of the other portion laterally from the opposite side of the machine as an advance portion during lateral cutting, and feed operating and controlling means operative to effect successive sumping and lateral cutting operations at either rib selectively connectible to said motor to draw in the sumping portion at a predetermined cutting speed and thereafter to draw in the advance portion at a predetermined cutting speed while permitting lengthening of said receding portion.
- 15 113. A mining machine slidable on a mine bottom comprising cutting mechanism adapted to be driven in either direction including a motor and an operatively connected cutter carrying cutter bar disposed longitudinally of said machine throughout the sumping and lateral cutting operations, and mechanism for sumping said bar into a face at either rib and thereafter feeding it laterally away from the selected rib with said cutting mechanism operating in the same direction as during sumping, said mechanism including a plurality of flexible feeding portions each having a free extremity, means for enabling at different ribs disposal of a different portion substantially longitudinally of the receding side of the machine during sumping and thereafter laterally as a receding portion during lateral cutting and for enabling disposal of the other portion laterally from the opposite side of the machine as an advance portion during lateral cutting, and feed operating and controlling means operative to effect successive sumping and lateral cutting operations at either rib selectively connectible to said motor to draw in the sumping portion at a predetermined cutting speed, to draw in the advance portion at a predetermined cutting speed while permitting lengthening of said receding portion, or to draw in one of said portions at a higher speed.
- 20 114. A mining machine slidable on a mine bottom comprising cutting mechanism adapted to be driven in either direction including a motor and an operatively connected cutter carrying cutter bar disposed longitudinally of said machine throughout the sumping and lateral cutting operations, and mechanism for sumping said bar into a face at either rib and thereafter feeding it laterally away from the selected rib with said cutting mechanism operating in the same direction as during sumping, said mechanism including a plurality of flexible feeding portions each having a free extremity, means for enabling at different ribs disposal of a different portion substantially longitudinally of the receding side of the machine during sumping and thereafter laterally as a receding portion during lateral cutting and for enabling disposal of the other portion laterally from the opposite side of the machine as an advance portion during lateral cutting, and feed operating and controlling means operative to effect successive sumping and lateral cutting operations at either rib selectively connectible to said motor to draw in the sumping portion at a predetermined cutting speed, to draw in the advance portion at a predetermined cutting speed while permitting lengthening of said receding portion, or to draw in either of said portions at a higher speed.
- 25 115. A mining machine slidable on a mine bottom comprising cutting mechanism adapted to be driven in either direction including a motor and an operatively connected cutter carrying cutter bar disposed longitudinally of said machine throughout the sumping and lateral cutting operations, and mechanism for sumping said bar into a face at either rib and thereafter feeding it laterally away from the selected rib with said cutting mechanism operating in the same direction as during sumping, said mechanism including a plurality of flexible feeding portions each having a free extremity, means for enabling at different ribs disposal of a different portion substantially longitudinally of the receding side of the machine during sumping and thereafter laterally as a receding portion during lateral cutting and for enabling disposal of the other portion laterally from the opposite side of the machine as an advance portion during lateral cutting, and feed oper-

- ating and controlling means operative to effect successive sumping and lateral cutting operations at either rib selectively connectible to said motor to draw in the sumping 5 then portion at a predetermined cutting speed and thereafter to draw in the then advance portion at the same predetermined cutting speed while permitting lengthening of said receding portion.
- 10 116. A mining machine slidable on a mine bottom comprising cutting mechanism adapted to be driven in either direction including a motor and an operatively connected cutter carrying cutter bar disposed longitudinally of said machine throughout the sumping and lateral cutting operations, and mechanism for sumping said bar into a face at either rib and thereafter feeding it laterally away from the selected rib with 15 said cutting mechanism operating in the same direction as during sumping, said mechanism including a plurality of flexible feeding portions each having a free extremity, means for enabling at different ribs 20 disposal of a different portion substantially longitudinally of the receding side of the machine during sumping and thereafter laterally as a receding portion during lateral cutting and for enabling disposal of the 25 other portion laterally from the opposite side of the machine as an advance portion during lateral cutting, and feed operating and controlling means operative to effect successive sumping and lateral cutting operations at either rib selectively connectible 30 to said motor to draw in the sumping portion at a predetermined cutting speed and thereafter to draw in the advance portion at the same predetermined cutting speed 35 while permitting lengthening of said receding portion, said means likewise having provision whereby each portion may be drawn in at the same predetermined higher speed.
117. A mining machine slidable on a mine bottom comprising cutting mechanism adapted to be driven in either direction including a motor and an operatively connected cutter carrying cutter bar disposed longitudinally of said machine throughout 40 the cutting operations, and feeding and guiding mechanism for sumping said bar into and thereafter feeding it laterally along a face in either direction with said cutting mechanism in either right or left 45 hand cutting rotating in the same direction as during the preceding sumping operation. said mechanism including a plurality of flexible feeding portions each having a free extremity, guiding means therefor for disposing either portion as the advancing portion on the advancing side of the machine or either portion as the receding portion substantially longitudinally of or laterally 50 from the receding side thereof, and winding means for said portions driven by said motor, said winding means for 55 disposing either portion as the advancing portion on the advancing side of the machine or either portion as the receding portion substantially longitudinally of or laterally 60 from the receding side thereof, and winding means for said portions driven by said motor, said winding means for 65 disposing either portion as the advancing portion on the advancing side of the machine or either portion as the receding portion substantially longitudinally of or laterally from the receding side thereof, and winding means for said portions driven by said motor.

motor, said winding means including a fast feed gear train and a slow feed gear train driven by said motor and means for drawing in either of said portions through said slow feed gear train without reversing the motor or one of the same through said fast feed gear train.

118. A mining machine slidable on a mine bottom comprising cutting mechanism adapted to be driven in either direction including a motor and an operatively connected cutter carrying cutter bar disposed longitudinally of said machine throughout the cutting operations, and feeding and guiding mechanism for sumping said bar into and thereafter feeding it laterally along a face in either direction with said cutting mechanism in either right or left hand cutting rotating in the same direction as during the preceding sumping operation, said mechanism including a plurality of flexible feeding portions each having a free extremity, guiding means therefor for disposing either portion as the advancing portion on the advancing side of the machine or either portion as the receding portion substantially longitudinally of or laterally from the receding side thereof, and winding means for said portions driven by said motor, said winding means including a fast feed gear train and a slow feed gear train driven by said motor, and means for drawing in either portion through either train without reversing the motor.

119. A mining machine slidable on a mine bottom comprising cutting mechanism adapted to be driven in either direction including a motor and an operatively connected cutter carrying cutter bar disposed longitudinally of said machine throughout the cutting operations, and feeding and guiding mechanism for sumping said bar into and thereafter feeding it laterally along a face in either direction with said cutting mechanism in either right or left hand cutting rotating in the same direction as during the preceding sumping operation, said mechanism including a plurality of flexible feeding portions each having a free extremity, guiding means therefor for disposing either portion as the advancing portion on the advancing side of the machine or either portion as the receding portion substantially longitudinally of or laterally from the receding side thereof, and winding means for said portions driven by said motor, said winding means including a fast feed gear train and a slow feed gear train driven by said motor, automatically releasable friction mechanism in either train, and means for drawing in either of said portions through said slow feed gear train without reversing the motor or one of the same through said fast feed gear train.

120. A mining machine slidable on a

mine bottom comprising cutting mechanism adapted to be driven in opposite directions including a motor and an operatively connected cutter carrying cutter bar disposed longitudinally of said machine throughout the cutting operations, and feeding and guiding mechanism for sumping said bar into and thereafter feeding it laterally along a face in either direction with said cutting mechanism in either right or left hand cutting rotating in the same direction as during the preceding sumping operation, said mechanism including a plurality of flexible feeding portions each having a free extremity, guiding means therefor for disposing either portion as the advancing portion on the advancing side of the machine or either portion as the receding portion substantially longitudinally of or laterally from the receding side thereof, and winding means for said portions driven by said motor, said winding means including fast and slow speed gearing connectible selectively to said motor in each direction of rotation thereof and of said cutter chain, automatically releasable friction mechanism in either train, and means for drawing in either portion through said slow feed gear train without reversing the motor or either of the same through said fast feed gear train.

121. A mining machine slidable on a mine bottom comprising cutting mechanism adapted to be driven in opposite directions including a motor and an operatively connected cutter carrying cutter bar disposed longitudinally of said machine throughout the cutting operations, and feeding and guiding mechanism for sumping said bar into and thereafter feeding it laterally along a face in either direction with said cutting mechanism in either right or left hand cutting rotating in the same direction as during the preceding sumping operation, said mechanism including a plurality of flexible feeding portions each having a free extremity, guiding means therefor for disposing either portion as the advancing portion on the advancing side of the machine or either portion as the receding portion substantially longitudinally of or laterally from the receding side thereof, and winding means for said portions driven by said motor, said winding means including fast and slow speed gearing connectible selectively to said motor in each direction of rotation thereof and of said cutter chain, and means for drawing in either portion through said slow feed gear train without reversing the motor or one portion through said fast gear train including automatically releasable friction mechanism controlling each feed and freely releasable manually to reduce either geared feed.

122. A mining machine slidable on a mine bottom comprising cutting mechanism

adapted to be driven in opposite directions including a cutter carrying cutter bar disposed longitudinally of said machine throughout the cutting operations, and feeding and guiding mechanism for sumping 70 said bar into and thereafter feeding it laterally along a face in either direction with said cutting mechanism in either right or left hand cutting rotating in the same direction as during the preceding sumping operation 75 123. A mining machine slidable on a mine bottom comprising cutting mechanism adapted to be driven in either direction including a motor and an operatively connected cutter carrying cutter bar disposed 100 longitudinally of said machine throughout the sumping and lateral cutting operations, and mechanism for sumping said bar into a face at either rib and thereafter feeding it laterally away from the selected rib with 105 said cutting mechanism operating in the same direction as during sumping, said mechanism including a plurality of flexible feeding portions each having a free extremity, feed operating and controlling 110 means operative at will to effect successive sumping and lateral cutting operations at either rib selectively connectible to said motor to draw in one portion at a predetermined cutting speed and thereafter to draw in the other portion at a predetermined cutting speed while permitting lengthening of said first mentioned portion, and means for enabling disposal of the free 115 end of either portion longitudinally of either side of the machine or laterally therefrom or enabling disposal of the free end of the other portion laterally from the other side of the machine without disturbing the arrangement of the remainder of the length 120 of said flexible portions relative to said feed operating means.

124. A mining machine slidable on a mine bottom comprising cutting mechanism adapted to be driven in either direction in 125

cluding a motor and an operatively connected cutter carrying cutter bar disposed longitudinally of said machine throughout the sumping and lateral cutting operations, 5 and mechanism for sumping said bar into a face at either rib and thereafter feeding it laterally away from the selected rib with said cutting mechanism operating in the same direction as during sumping, said 10 mechanism including a plurality of flexible feeding portions each having a free extremity, means for enabling at different ribs disposal of a different portion substantially longitudinally of the receding side of the 15 machine during sumping and thereafter laterally as a receding portion during lateral cutting and for enabling disposal of the other portion laterally from the opposite side of the machine as an advance portion 20 during lateral cutting, and feed operating means operative to effect successive sumping and lateral cutting operations at either rib including a single feed operating member selectively connectible to said motor to draw 25 in the sumping portion at a predetermined cutting speed and thereafter to draw in the advance portion at a predetermined cutting speed while permitting lengthening of said receding portion.

30 125. A mining machine slidable on a mine bottom, comprising cutting mechanism adapted to be driven in either direction including a motor and an operatively connected cutter carrying cutter bar disposed 35 longitudinally of said machine throughout the sumping and lateral cutting operations, and mechanism for sumping said bar into a face at either rib and thereafter feeding it laterally away from the selected rib with 40 said cutting mechanism operating in the same direction as during sumping, said mechanism including a continuous flexible feeding member provided with a plurality of flexible feeding portions each having a 45 free extremity, means for enabling at different ribs disposed of a different portion substantially longitudinally of the receding side of the machine during sumping and thereafter laterally as a receding portion 50 during lateral cutting and for enabling disposal of the other portion laterally from the opposite side of the machine as an advance portion during lateral cutting, and feed operating and controlling means operative to 55 effect successive sumping and lateral cutting operations at either rib selectively connectible to said motor to draw in the sumping portion at a predetermined cutting speed and thereafter to draw in the advance portion 60 at a predetermined cutting speed while permitting lengthening of said receding portion.

126. In a mining machine, flexible feeding means including a plurality of flexible 65 feeding portions each having a free ex-

tremity, winding means for each of the same, power driven transmission mechanism including differential gearing comprising cooperating internally and externally toothed sets of gears, and means for connecting said winding means and said transmission mechanism in different relations to operate said winding means to draw in either portion at different speeds. 70

127. In a mining machine, flexible feeding 75 means including a plurality of flexible feeding portions each having a free extremity, winding means for either of the same, power driven transmission mechanism including epicyclic differential gearing comprising cooperating internally and externally toothed sets of gears, and means for connecting said winding means and said transmission mechanism in different relations to operate said winding means to draw in either portion at 80 different speeds.

128. A room and pillar mining machine adapted to cut in either direction having reversible cutting mechanism including a cutter bar projecting longitudinally from 90 said machine during sumping and transverse cutting and flexible advance and receding portions and provision whereby in either direction of operation of said cutting mechanism without reversing the same said 95 machine may be summed at a cutting speed relative to a receding portion extending along its receding side and subsequently moved transversely at a cutting speed of a similar order relative to its advance portion 100 while between the latter and said receding portion.

129. A room and pillar mining machine adapted to cut in either direction having reversible cutting mechanism including a 105 cutter bar projecting longitudinally from said machine during sumping and transverse cutting and carrying a cutter chain circulated in opposite directions during cutting in opposite directions, and flexible advance 110 and receding portions and provision whereby in either direction of operation of said cutting mechanism without reversing the same and with only one setting of the jacks said machine may be summed at a cutting 115 speed relative to a receding portion extending along its receding side and subsequently moved transversely at a cutting speed of a similar order relative to its advance portion 120 while between the latter and said receding portion.

130. A room and pillar mining machine adapted to cut in either direction having reversible cutting mechanism including a cutter bar projecting longitudinally from said 125 machine during sumping and cutting across a face and a cutter chain circulating in opposite directions to cut and clear oppositely extending kerfs and flexible advance and receding portions and provision whereby in 130

either direction of operation of said cutting mechanism without interrupting the operation thereof or reversing the same said machine may be sumped at a cutting speed 5 relative to a receding portion extending along its receding side and subsequently moved transversely at a cutting speed relative to its advance portion and while between the latter and said receding portion 10 in a substantially continuous progress into and across the face with said portions acting on opposite ends of the machine frame.

131. A room and pillar mining machine adapted to cut in either direction having 15 reversible cutting mechanism including a cutter bar projecting longitudinally from said machine during sumping and cutting across a face and a cutter chain circulating in opposite directions to cut and clear 20 oppositely extending kerfs and flexible advance and receding portions and provision whereby in either direction of operation of said cutting mechanism without reversing the same and while free to draw in either portion 25 at will said machine may be sumped at a cutting speed relative to a receding portion extending along its receding side and subsequently moved transversely at a cutting speed relative to its advance portion 30 while between the latter and said receding portion with said portions acting on opposite ends of the machine frame.

132. A room and pillar mining machine adapted to cut in either direction having 35 reversible cutting mechanism including a cutter bar projecting longitudinally from said machine during sumping and cutting across a face and a cutter chain circulating in opposite directions to cut and clear 40 oppositely extending kerfs and flexible advance and receding portions and provision whereby in either direction of operation of said cutting mechanism without reversing the same and while free to draw in either portion 45 at will at a predetermined slow or cutting speed said machine may be sumped at a cutting speed relative to a receding portion extending along its receding side and subsequently moved transversely at a cutting 50 speed relative to its advance portion and while between the latter and said receding portion with said portion acting on opposite ends of the machine frame.

133. A room and pillar mining machine adapted to cut in either direction having 55 reversible cutting mechanism including a cutter bar projecting longitudinally from said machine during sumping and cutting across a face and a cutter chain circulating 60 in opposite directions to cut and clear oppositely extending kerfs and flexible advance and receding portions and provision whereby in either direction of operation of said cutting mechanism without reversing the 65 same and while free to draw in either por-

tion at will at a predetermined slow or cutting speed or at a higher speed said machine may be sumped at a cutting speed relative to a receding portion extending along its receding side and subsequently moved transversely at a cutting speed relative to its advance portion and while between the latter and said receding portion. 70

134. A room and pillar mining machine including a motor having a power shaft extending longitudinally of said machine, cutting mechanism including a cutter bar mounted on the machine in permanent longitudinally projecting relation thereto, a cutter chain on said bar, and a cutter chain driving sprocket rotating on a vertical axis to the rear of said motor, and feeding means including flexible advance and receding portions, guiding means whereby the advance portion may be extended longitudinally 75 along the advancing side of the machine and laterally from the front end of the machine frame to an anchor at its rib and the receding portion may be extended longitudinally along the receding side of the machine and anchored to the opposite rib, and feed operating means wholly disposed to the rear of the forward end of said motor and actuated by one end of its shaft whereby the machine may be thereafter moved relative to the receding portion to make the sumping cut and then without reversing said cutting 80 mechanism moved laterally under control of said receding portion without shifting the position of the anchor for said advance portion. 85

135. A room and pillar mining machine including a motor having a power shaft extending longitudinally of said machine, cutting mechanism including a cutter bar mounted on the machine in permanent longitudinally projecting relation thereto, a cutter chain on said bar, and a cutter chain driving sprocket rotating on a vertical axis to the rear of said motor, and feeding means 100 including flexible advance and receding portions, guiding means whereby the advance portion may be extended longitudinally along the advancing side of the machine and laterally from the front end of the machine frame to an anchor at its rib and the receding portion may be extended longitudinally 105 along the receding side of the machine to an anchor at the opposite rib, and feed operating means wholly disposed to the rear of the forward end of said motor and actuated by one end of its shaft whereby the machine may be thereafter moved relative to the receding portion to make the sumping cut and then without reversing said cutting mechanism moved laterally under control of said receding portion without shifting the position of the anchor for said advance portion. 110

136. A room and pillar mining machine including a motor having a power shaft extending longitudinally of said machine, cutting mechanism including a cutter bar mounted on the machine in permanent longitudinally projecting relation thereto, a cutter chain on said bar, and a cutter chain driving sprocket rotating on a vertical axis to the rear of said motor, and feeding means including flexible advance and receding portions, guiding means whereby the advance portion may be extended longitudinally 115 along the advancing side of the machine and laterally from the front end of the machine frame to an anchor at its rib and the receding portion may be extended longitudinally of the receding side of the machine to an anchor at the opposite rib, and feed operating means wholly disposed to the rear of the forward end of said motor and actuated by one end of its shaft whereby the machine may be thereafter moved relative to the receding portion to make the sumping cut and then without reversing said cutting 120 mechanism moved laterally under control of said receding portion without shifting the position of the anchor for said advance portion or changing the relation of said portion to its guiding means. 125

136. A room and pillar mining machine including a motor having a power shaft extending longitudinally of said machine, cutting mechanism including a cutter bar 5 mounted on the machine in permanent longitudinally projecting relation thereto, a cutter chain on said bar, and a cutter chain driving sprocket rotating on a vertical axis to the rear of said motor, and feeding means 10 including flexible, advance and receding portions, guiding means whereby the advance portion may be operatively extended directly from the rear end of the machine frame laterally to an anchor at its rib and the receding portion may be extended longitudinally 15 of the receding side of the machine and anchored to its rib, supplemental guiding means at opposite sides of the front end of the machine frame each selectively engageable by its portion, and feed operating means wholly disposed to the rear of the forward end of said motor and actuated by one end of its shaft whereby whether said portions engage said supplemental guiding 20 means or not during sumping the machine may be moved relative to the receding portion during sumping and then without reversing said cutting mechanism moved laterally under control of said receding portion 25 and between its portions without shifting the position of the advance anchor.
137. A room and pillar mining machine 30 slidable on a mine bottom comprising an electric motor, cutting mechanism driven thereby including a cutter carrying cutter bar extending longitudinally of said machine throughout cutting, and feeding and guiding mechanism for sumping said bar into and thereafter feeding it laterally along a face with said cutting mechanism rotating in the same direction as during the sumping operation, said mechanism including advance and receding flexible feeding portions each having a free extremity, guiding 35 means for said portions whereby said machine may be sumped and moved laterally, and winding means for said feeding mechanism driven by said motor, said winding means including a fast feed gear train 40 and a slow feed gear train and means for selectively drawing in either portion through either train without reversal of the rotation of said motor.
138. A room and pillar mining machine 45 slidable on a mine bottom comprising an electric motor, cutting mechanism driven thereby including a cutter carrying cutter bar extending longitudinally of said machine throughout cutting, and feeding and guiding mechanism for sumping said bar into and thereafter feeding it laterally along a face with said cutting mechanism rotating in the same direction as during the sumping operation, said mechanism including advance and receding flexible feeding portions 50
- each having a free extremity, guiding means for said portions whereby said machine may be sumped along one of said portions and then moved laterally between said portion and the advance portion, and winding means for said feeding mechanism driven by said motor, said winding means including a fast feed gear train and a slow feed gear train and means for selectively drawing in either portion through either train without interruption of the rotation of said motor. 70
139. A room and pillar mining machine 75 slidable on a mine bottom comprising an electric motor, cutting mechanism driven thereby including a cutter carrying cutter bar, extending longitudinally of said machine throughout cutting and feeding and guiding mechanism for sumping said bar into and thereafter feeding it laterally along a face with said cutting mechanism rotating in the same direction as during the sumping operation, said mechanism including advance and receding flexible feeding portions 80 each having a free extremity, guiding means for said portions whereby said machine may be sumped along one of said portions and then moved laterally between said portion and the advance portion, and winding means for said feeding mechanism driven by said motor, said winding means including a fast feed gear train and a slow feed gear train and means for selectively drawing in one of said portions through either of said trains or the other portion through one of said trains without reversal of said motor. 85
140. A room and pillar mining machine 90 slidable on a mine bottom comprising an electric motor having an armature shaft, cutting mechanism driven by one end of said shaft including a cutter carrying cutter bar, and feeding and guiding mechanism for sumping said bar into and thereafter feeding it laterally along a face with said cutting mechanism rotating in the same direction as during the sumping operation, said mechanism including flexible feeding portions each having a free extremity, guiding 95 means therefor whereby said machine may be sumped along one of said portions and then moved laterally between said portion and an advance portion, and winding means driven by the same end of said shaft, said winding means including a fast feed gear train and a slow feed gear train adapted to 100 be driven by said motor and means for drawing in either portion through either train without reversal of said motor. 105
141. A room and pillar mining machine 110 slidable on a mine bottom comprising an electric motor, cutting mechanism driven by said motor including a cutter carrying cutter bar extending longitudinally of said machine throughout cutting, and feeding and guiding mechanism for sumping said 115
- 120
- 125
- 130

- bar into a face at either rib and thereafter feeding it laterally away from the rib with said cutting mechanism rotating in the same direction as during the sumping operation, said mechanism including flexible feeding portions each having a free extremity, guiding means therefor whereby said machine may be sumped along a portion at either rib and then moved laterally away from the rib between said portion and an advance portion, and winding means for said feeding mechanism, said winding means including a fast feed gear train and a slow feed gear train adapted to be driven by said motor and means for drawing in either portion through either train without reversal of said motor.
142. A room and pillar mining machine 20 slidable on a mine bottom comprising an electric motor having an armature shaft, cutting mechanism driven by one end of said shaft including a cutter carrying cutter bar, and feeding and guiding mechanism for sumping said bar into a face at either rib 25 and thereafter feeding it laterally away from the rib with said cutting mechanism rotating in the same direction as during the sumping operation, said mechanism including flexible feeding portions each having a free extremity, guiding means therefor whereby said machine may be sumped along a different portion at different ribs and then moved laterally away from the rib between said portion and an advance 30 portion, and winding means for said feeding mechanism driven by the same end of said armature shaft, said winding means including a fast feed gear train and a slow feed gear train adapted to be driven by said 35 motor and means for drawing in either portion through either train without interruption of the rotation of said motor.
143. The combination with a mining machine including a frame 40 slidable on a mine bottom and comprising a motor having a power shaft and a projecting cutter bar parallel to said power shaft during sumping and transverse cutting, of flexible feeding means for feeding said frame laterally including 45 flexible feeding portions disposable in opposite directions from the opposite ends thereof, and feed operating and controlling means operative to wind in the advance portion and lengthen the receding portion and having power connections with one end only of said shaft for winding in said receding portion at a predetermined speed during cutting and also at a higher speed in excess of the cutting capacity of the machine under normal working conditions, said feed operating and controlling means being operative to effect each of said winding operations while the mode of operative connection thereof with said portion 50 remains the same and with said shaft rotating in the same direction.
144. The combination with a mining machine including a frame 55 slidable on a mine bottom and comprising a motor having a power shaft and a projecting cutter bar parallel to said power shaft during sumping and transverse cutting, of flexible feeding means for feeding said frame laterally including flexible feeding portions disposable in opposite directions from the opposite ends thereof, and feed operating and controlling means operative to wind in the advance portion and lengthen the receding portion having power connections with one end only of said shaft for winding in said receding portion at a predetermined speed during cutting and also at a higher speed in excess of the cutting capacity of the machine under normal working conditions, said feed operating and controlling means being operative to effect each of said winding operations while the mode of operative connection thereof with said portion 60 remains the same and with said shaft rotating in the same direction.
145. The combination with a mining machine including a frame 65 slidable on a mine bottom and comprising a motor having a power shaft and a projecting cutter bar parallel to said power shaft during all cutting operations, of flexible feeding means for feeding said frame laterally including flexible feeding portions disposable in opposite directions from the opposite ends thereof, and feed operating and controlling means actuated during winding wholly by one end of said power shaft and operative to wind in the advance portion and lengthen the receding portion and including gearing geared to wind in said receding portion by power at a predetermined speed during cutting and also at a higher speed in excess of the cutting capacity of the machine under normal conditions, said feed operating and controlling means being operative to effect each of said winding operations while the mode of operative connection thereof with said portion 70 remains the same and with said shaft rotating in the same direction.
146. The combination with a mining machine including a frame 75 slidable on a mine bottom and comprising a motor having a power shaft and a projecting cutter bar parallel to said power shaft during all cutting operations, of flexible feeding means for feeding said frame laterally including flexible feeding portions disposable in opposite directions from the opposite ends thereof, and feed operating and controlling means actuated during winding wholly by one end of said power shaft and operative to wind in the advance portion and lengthen the receding portion and including gearing geared to wind in said receding portion by 80

power at a predetermined speed during cutting and also at a predetermined higher speed.

147. A room and pillar mining machine including a frame slideable on a mine bottom and a rigidly projecting cutter bar and flexible feeding means for feeding said frame laterally including a single continuous flexible feeding member providing flexible feeding portions disposable in opposite directions from the opposite ends of said machine frame and determining its angular relation to a working face, and feed operating and controlling means operative to wind in the advance portion and lengthen the receding portion and including a motor having a power shaft parallel to the major dimension of said bar and having driving connections only with its rear end, gearing geared to wind in the receding portion by power at a predetermined speed during cutting, and cooperating adjustable controlling friction mechanism, said feed operating and controlling means being operative to effect each of said aforesaid winding operations without change in the mode of operative connection with said portions or reversal of said motor.

148. The combination with a mining machine including a frame slideable on a mine bottom and a projecting cutter bar secured thereto in alinement therewith during sumping and cutting, of flexible feeding means for feeding said frame laterally including flexible feeding portions disposable in opposite directions from the opposite ends thereof and determining its angular relation to a working face, and feed operating and controlling means operative to wind in the advance portion and lengthen the receding portion and including a motor having a power shaft parallel to the major dimension of said bar and having driving connections only with its rear end, gearing geared to wind in said receding portion by power at a predetermined speed during cutting and also at a higher speed in excess of the cutting capacity of the machine under normal working conditions, and cooperating adjustable frictional controlling mechanism, said feed operating and controlling means being operative to effect each of said aforesaid winding operations without change in the mode of operative connection with said portions or reversal of said motor.

149. The combination with a mining machine including a frame slideable on a mine bottom, a projecting cutter bar secured thereto in alinement therewith during sumping and cutting and a motor whose axis of rotation extends longitudinally of said frame, of flexible feeding means for feeding said frame laterally including flexible feeding portions disposable in opposite direc-

tions from the opposite ends thereof and determining its angular relation to a working face, and feed operating and controlling means arranged to the rear of the front end of said motor and having operative connections with one end only of the latter and operative to wind in the advance portion and lengthen the receding portion by power at a predetermined speed during cutting and also at a predetermined higher speed and cooperating adjustable frictional controlling mechanism, said feed operating and controlling means being operative to effect each of said aforesaid winding operations without change in the mode of operative connection with said portions or reversal of said motor.

150. The combination with a mining machine including a frame slideable on a mine bottom and a projecting cutter bar rigidly secured thereto in alinement therewith during all cutting operations, of flexible feeding means for feeding said frame laterally including flexible feeding portions disposable in opposite directions from the opposite ends thereof and determining the angular position thereof relative to a working face, a motor having a longitudinally extending axis, and feed operating and controlling means operative to wind in the advance portion and lengthen the receding portion and having power connections with but one end of said motor for winding in either of said portions at a predetermined speed and also at a higher speed, said feed operating and controlling means being operative to effect each of said aforesaid winding operations without change in the mode of operative connection with said portions or reversal of said motor.

151. The combination with a mining machine including a frame slideable on a mine bottom and a projecting cutter bar rigidly secured thereto in alinement therewith during all cutting operations, of flexible feeding means for feeding said frame laterally including flexible feeding portions disposable in opposite directions from the opposite ends thereof and determining the angular position thereof relative to a working face, a motor having a longitudinally extending axis, and feed operating and controlling means operative to wind in the advance portion and lengthen the receding portion and having power connections with but one end of said motor for winding in either of said portions at a predetermined speed and also at a higher predetermined speed, said feed operating and controlling means being operative to effect each of said aforesaid winding operations without change in the mode of operative connection with said portions or reversal of said motor.

152. The combination with a mining machine including a frame slideable on a mine

- bottom, a projecting cutter bar, and a motor whose axis is parallel to the major dimension of said bar during cutting, said motor having driving connections only with its rear end of flexible feeding means for feeding said frame laterally including flexible feeding portions disposable in opposite directions from the opposite ends thereof and determining the angular position thereof relative to a working face, and feed operating and controlling means operative to wind in the advance portion and lengthen the receding portion and including gearing including change speed gearing common to the drawing in of both portions and geared to wind in either of said portions by power at a predetermined speed during cutting and also at a higher speed, said feed operating and controlling means being operative to effect each of aforesaid winding operations without change in the mode of operative connection with said portions or reversal of said motor.
153. The combination with a mining machine including a frame slidable on a mine bottom, a projecting cutter bar, and a motor whose axis is parallel to the major dimension of said bar during cutting, said motor having driving connections only with its rear end of flexible feeding means for feeding said frame laterally including flexible feeding portions disposable in opposite directions from the opposite ends thereof and determining the angular position thereof relative to a working face, and feed operating and controlling means operative to wind in the advance portion and lengthen the receding portion and including gearing including change speed gearing common to the drawing in of both portions geared to wind in either of said portions by power at a predetermined speed during cutting and also at a higher predetermined speed, said feed operating and controlling means being operative to effect each of aforesaid winding operations without change in the mode of operative connection with said portions or reversal of said motor.
154. A room and pillar mining machine including a frame slidable on a mine bottom and a permanently longitudinally projecting cutter bar and flexible feeding means for feeding said frame laterally including a single continuous flexible feeding member providing flexible feeding portions disposable in opposite directions from the opposite ends of said machine frame and controlling its angular relation to a working face, and feed operating and controlling means operative to wind in the advance portion and lengthen the receding portion and including a motor comprising a rotor parallel to the major dimension of said bar and gearing actuated thereby and geared to wind in either of said portions by power at a predetermined speed during cutting, and cooperating adjustable frictional controlling mechanism, said feed operating and controlling means being operative to effect each of said aforesaid winding operations without change in the mode of operative connection with said portions or reversal of said motor.
155. The combination with a mining machine including a frame slidable on a mine bottom and a projecting cutter chain carrying cutter bar rigidly secured throughout cutting in alinement with said frame, of flexible feeding means for feeding said frame laterally including flexible feeding portions disposable in opposite directions from the opposite ends thereof and operative to determine the angle of the frame to the face, and feed operating and controlling means operative to wind in the advance portion and lengthen the receding portion and including rotatable winding means on said frame fixed as to movement of translation relative thereto, and actuating means for said winding means including common gearing geared to cause said winding means selectively to wind in either of said portions by power at a predetermined speed during cutting and also at a higher speed and cooperating adjustable frictional controlling mechanism, said feed operating and controlling means being operative to effect each of said aforesaid winding operations without change in the mode of operative connection with said portions or reversal of said motor.
156. The combination with a mining machine including a frame slidable on a mine bottom and a projecting cutter chain carrying cutter bar rigidly secured throughout cutting in alinement with said frame, of flexible feeding means for feeding said frame laterally including flexible feeding portions disposable in opposite directions from the opposite ends thereof and operative to determine the angle of the frame to the face, and feed operating and controlling means operative to wind in the advance portion and lengthen the receding portion and including rotatable winding means on said frame fixed as to movement of translation relative thereto, and actuating means for said winding means including common gearing geared to cause said winding means selectively to wind in either of said portions by power at a predetermined speed during cutting and also at a higher predetermined speed and cooperating adjustable frictional controlling mechanism, said feed operating and controlling means being operative to effect each of said aforesaid winding operations without change in the mode of operative connection with said portions or reversal of said motor.
157. In a room and pillar mining ma-

chine having permanently fixedly longitudinally projecting cutting mechanism and 5
slidable directly on a mine bottom, a driving motor operatively connected to the cutting mechanism, machine feeding and guiding mechanism including a plurality of flexible feeding portions each having a free extremity and extending laterally from opposite ends of said machine, one of said portions constituting an advancing portion and 10
the other a receding portion during cutting across a face, and means driven by said motor for winding in that portion which constitutes the receding portion at a plurality of predetermined speeds, said means being friction controlled at each speed and comprising a member rotatable during winding in of said portion, a plurality of members coaxial therewith, and controlling 15
means for said members operative to prevent simultaneous operation of said controlling means.

158. A mining machine slidable on a mine bottom comprising a machine frame, cutting mechanism permanently mounted thereon in fixed longitudinal relation thereto, a motor on said machine frame actuating said cutting mechanism, and a plurality of guiding members arranged respectively at diagonally opposite corners of said frame, 20
a flexible feeding portion extending about the rearward one of said guiding members and having a free end, and means operable by said motor without reversal thereof for winding in said portion at a plurality of predetermined speeds frictionally controlled at each speed and comprising a pair of coaxial members rotating on vertical axes and alternatively cooperating in effecting winding in of said flexible portion. 25

MORRIS P. HOLMES.

Certificate of Correction.

It is hereby certified that in Letters Patent No. 1,544,067, granted June 30, 1925, upon the application of Morris P. Holmes, of Claremont, New Hampshire, for an improvement in "Mining Machines," errors appear in the printed specification requiring correction as follows: Page 1, line 67, for "overloading" read *overload*, and line 93, for the misspelled word "cuter" read *cutter*; page 4, line 4, beginning with the word "Here" strike out all to and including the word, numeral, and period "Fig. 9." in line 13 and insert the same to follow after the word "described," line 22; page 5, line 32, for "change" read *changes*; page 8, line 7, claim 3, after "conditions" insert a comma; line 16, claim 4, for "flexible" read *a*; line 18, before "feeding" insert *flexible*; line 98, claim 8, after "frame" strike out the comma; line 125, claim 9, after "frame" strike out the comma and insert the same after "cutting" in the same line; page 9, line 53, claim 11, for "feeding" read *feed*; page 10, line 47, claim 16, for "said" read *and*; page 14, lines 87 and 88, claim 38, for "said members" read *the same*; line 100, claim 39, after "same" insert a comma; lines 101 to 103, claim 39, strike out "including a controlling member for said reversing mechanism disposable in different positions during reverse operations," and line 105, after "said" insert the word *reverse*; page 16, line 15, claim 56, after "face" insert a comma; line 23, same claim, after "speed" strike out the comma; line 37, claim 57, after "face" insert a comma, and line 47, after "speed" strike out the comma; page 17, line 81, claim 74, for "manually" read *mutually*; page 18, line 27, claim 80, before "speed" insert *and*, and lines 101 and 102, claim 84, strike out the words "or interruption of drive" and insert the same before the word "of," line 105, same claim; page 24, line 79, claim 109, strike out the words "common to all feeds and" and insert the same after the word "means," line 77, same claim; page 26, line 4, claim 115, after the article "the" insert *then*, and line 5, strike out "then"; page 28, line 46, claim 125, for the word "disposed" read *disposal*; page 30, line 25, claim 136, after "sumping" insert a comma; line 82, claim 139, after "bar" strike out the comma, and line 83, after "cutting" insert a comma; page 33, line 5, claim 152, and line 30, claim 153, after "end" insert a comma; and that the said Letters Patent should be read with these corrections therein that the same may conform to the record of the case in the Patent Office.

Signed and sealed this 8th day of December, A. D. 1925.
